SWITCH AND SIGNAL CONTROL SYSTEM
FOR RAILROADSNelson B. Coley, Rochester, N. Y., assignor to
General Railway Signal Company, Rochester,
N. Y.

Application April 10, 1940, Serial No. 328,908

19 Claims. (Cl. 246—134)

This invention relates to switch and signal control systems for railroads, and it more particularly pertains to such systems of the entrance-exit type.

In an entrance-exit type of switch and signal control system, a control machine at a control office has a control panel upon which a miniature track diagram of the track layout is located and upon such diagram is disposed buttons for the entrance and exit ends of each of the routes extending through the track layout between route ends which are usually defined by the location of wayside signals. The establishment of each route through the track layout is accomplished in response to the designation by an operator of the respective entrance and exit ends of that route by the actuation of the control buttons on the control panel for the respective entrance and exit points.

It is further provided in some entrance-exit systems that an operator, in designating a route to be established extending past several signals, be required to actuate only the buttons for the extreme ends of that route, thus providing "through route" or "end-to-end" control past the intermediate signals included between the extreme entrance and exit ends of that route. In such systems, it is also provided that a through route can be set up by designating the entrance and exit ends of each track portion or interlocked group in such through route, as well as by through route control. It is to be understood that an interlocked group comprises one or more track switches interconnecting different stretches of track for setting up routes over such stretches of track between signals for the ends of the routes.

One object of the present invention is to provide in accordance with the operating requirements of railway practice, that manipulation to establish through routes is effective only for routes governed by one class of signals, such, for example, as by high speed signals, and it is not effective for the establishment of routes governed by another class of signals, such for example, as low speed signals.

More specifically, in setting up a through route extending through several interlocked groups, the establishment of a route in each of those interlocked groups and the clearing of the high speed signal for the entrance to each of such groups can be effected only by manipulation of the control buttons for the extreme ends of such through route in a manner characteristic of high speed signal control. The manipulation of the same

buttons in a manner characteristic of low speed signal control fails to establish any route and fails to clear any signals. However, the manipulation of the control buttons for the entrance and exit ends of any route within a single interlocked group in a manner characteristic of the low speed signal control, effects the establishment of that route and the clearing of the proper low speed entering signal. In other words, the designation 5 of an entrance point for the establishment of a route renders end-to-end control effective or ineffective for that route, dependent upon the distinctive character of the manipulation for the entrance end of such route.

10 This invention is to be considered as an improvement over the entrance-exit system disclosed in the prior patent of S. N. Wight, Patent No. 2,265,258, dated December 9, 1941, and no claim is made herein to anything disclosed in that application. In that application a circuit network conveniently called an "initiating network" is provided for each direction of traffic for energizing selecting relays for the trailed track switches and for conditioning exit relays for each 15 of the exit points, that is, the designation of an entrance point energizes the selecting relays for certain switches trailed in the various routes originating at that entrance point dependent upon the availability for use of such routes, and 20 also conditions for energization the exit relays for the ends of such available routes ready for energization upon the actuation of its associated control button. Each of the initiating circuit networks includes circuit selections in branches 25 or circuit portions to conform to the track layout for which the system is provided so that energy is fed through each branch of the circuit network corresponding to a route, when an entrance point is designated, only so far as the portions of track 30 corresponding to such branches are available for use. Thus, where through route control is provided, the designation of an entrance point causes energy to feed through the branches of the initiating network corresponding to the available routes of the track layout, even when those 35 routes extend through several interlocked groups, such energization of the initiating network being indiscriminate of the particular kind or class of signal at the entrance point which is designated 40 by an operator.

Another object of the present invention is to employ polarized initiating circuits so that energy of one polarity will flow through each of the various branches of the initiating circuit network responsive to the designation of an entrance point

only so far as such branches correspond to a route or routes included within that single interlocked group with which such entrance point is associated, if the designation of that entrance point has been characterized for the clearing of a low speed or dwarf signal. If, however, the operator has distinctively actuated the button for that entrance point in a manner to clear a high speed signal, energy of the opposite polarity will flow through each of the various branches of the initiating network corresponding with available routes extending from that entrance point, even if such routes extend through several interlocked groups. This energy which flows over the initiating networks in response to the designation of an entrance point, whether for routes within the same interlocked group or for through routes originating at that entrance point, prepares for energization the exit relays for the exit ends of such of those routes as are then available for use, so that the actuation of the control button associated with any such exit relay to designate an exit end of one of such available routes causes that exit relay to be picked up and that particular route to be established as well as the clearing of its governing signal.

Thus, the system of the present invention is so organized that the distinctive actuation of a control button to designate an entrance point determines whether a control button can be effective, when subsequently actuated, to designate an exit point within the same interlocked group to establish a route governed by a low speed signal, or whether a control button can be effective, when subsequently actuated, to designate the exit end of some through route governed by high speed signals.

According to the above description, it will be understood that the embodiment of the present invention provides means for limiting the use of low speed signals to routes within their associated interlocked group. Also, it will be seen that the high speed signals may also govern traffic over certain of the same routes that have low speed signals for governing traffic thereover, with the system so organized that the character of the distinctive actuation of a control button to designate an entrance signal location acts to determine whether the low speed or the high speed signal shall be used for the particular route to be set up. Although such an arrangement is highly desirable, it may happen that certain entrance points will have routes originating thereat which should have traffic governed thereover only by low speed signals. In other words, there may be certain routes within a single interlocked group of such a nature that no high speed signal should be cleared at any time to allow traffic to pass over such routes. Therefore, another object of the present invention is to provide means for limiting the use of high speed signals to only those routes which may have high speed traffic, and in accordance with the present invention this is accomplished through the medium of the polarized initiating networks above mentioned. When the present invention is applied to any particular installation, it is then determined which routes shall have only low speed signals governing traffic thereover so that whether a low speed signal or a high speed shall be provided for such routes is then no longer under the control of the operator of such a system, although the manual manipulation for the entrance ends of such routes may be required to be of the same distinctive character as provided

for the entrance signal locations for those routes where the operator may choose as to whether a low speed or a high speed signal shall be cleared.

Another object of the present invention is to provide means for embodying the principles of the invention in such a manner that such means can be readily adapted for use in accordance with various practices of foreign railways. Such foreign practices differ in many respects from 10 the operating practices generally known in this country because of the radically different operating rules under which such foreign railroads are required to function. One form of foreign practice is to provide separate signals for high and 15 low speed train movements which are conveniently termed "running" and "shunting" signals, respectively, which shunt signals are used primarily for switching operations; while the running signals are used for train movements 20 continuing through an interlocking plant, and when a train is proceeding on such "running signals" the engineer ignores the condition of the shunt signals. In other words, the establishment of a route governed by a "running signal" is completed past "shunt signals", without 25 clearing those shunt signals which may be intermediate to the cleared running signal and the next running signal for governing traffic in the same direction, or to an arbitrary point as the 30 exit end of the route. The control of the shunt signals differs from practice in this country in that, when several shunt signals are to be cleared for traffic approaching a particular point in the track layout, it is required that any given one of such shunt signals can be cleared only when the 35 next shunt signal in advance is cleared. It is further provided that the setting up of routes governed by shunt signals cannot be effected by end-to-end or through route control.

The present invention is therefore particularly adaptable to these differing practices by the use of control buttons which may be distinctly actuated in combination with polarized initiating circuits for causing the different entrance-exit manipulations of a control machine to be co-extensive with the extent of trackway over which the signals of the different classes may govern traffic.

It is believed that other objects, purposes and 50 characteristic features of the present invention will be more readily understood from reference to the accompanying drawings and as they are pointed out hereinafter in the description of the present invention.

In describing the invention in detail, reference will be made to the accompanying drawings in which corresponding parts are designated by corresponding reference characters as they appear throughout the several drawings, in which similar letter reference characters are used to designate parts of the same general nature, such parts being usually made distinctive by reason of preceding numerals or by preceding letter reference characters representative of the signal locations, and in which:

Figs. 1A and 1B, when placed side by side, illustrate the track diagram on a section of the control panel of a control machine for the track layout for which the present embodiment of the invention is provided, together with circuit means for establishing each desired route according to railroad practice in this country through the track layout and for clearing the signal governing entrance thereto;

Fig. 2 illustrates the track layout for which this

embodiment of the present invention is provided, together with various typical control circuits relative to the safe operation of the track switches and the governing of the signals;

Figs. 3A and 3B, when placed side by side, 5 illustrate a portion of the control panel of a control machine having a miniature track diagram corresponding to the track layout illustrated in Fig. 2, together with circuit means for the establishment of routes through the track layout and the clearing of signals governing entrance to such routes in accordance with the requirements of foreign railway practice;

Fig. 4 illustrates how the route locking is modified from the form shown in Fig. 2 in order to 15 conform to foreign railway practice; and

Fig. 5 illustrates diagrammatically a typical signal mechanism used in the embodiment of the present invention.

Rather than show the specific construction and arrangement of parts that would be employed in practice, the drawings have been arranged to disclose as clearly as possible the mode of operation of the system and the principles involved. Thus, the various relays and their contacts are shown in a conventional manner, corresponding relays and corresponding contacts being readily identified throughout the drawings by like reference characters. Certain circuit details well known to those familiar with the art 20 are merely indicated by dotted lines, and symbols are used to indicate connections to the terminals of batteries or other sources of electric current instead of showing all of the wiring connections to such terminals.

The symbols (+) and (−) are employed to indicate the positive and negative terminals respectively of suitable batteries or other sources of direct current, and the circuits with which those symbols are used always have current flowing in 25 the same direction. The symbols (B+) and (B−) are used to indicate connections to the opposite terminals of a suitable battery, or other direct current source which has a central or intermediate tap designated (CN); and the circuits with which those symbols are used may have current flowing in one direction or the other dependent upon the particular terminal used in 30 combination with the intermediate tap (CN).

Reference is made from time to time in the description to functions common to all parts of a similar kind or class by use of the letter reference characters common to such parts without their distinctive preceding numerals or letters representative of signal locations for the purpose of facilitating in the description of the present invention, such a reference being understood to apply to each of the parts in that particular class.

Track layout.—With reference to Fig. 2 of the accompanying drawings, the track layout for this embodiment of the present invention consists of a main track having two other tracks connected thereto by single track switches 2 and 3 respectively. It is to be understood that the simple track layout chosen for the disclosure of the present invention is chosen primarily for the purpose of simplifying the disclosure as to the mode of operation and the principles involved, rather than to limit the scope of the present invention, inasmuch as the present invention embodies principles which make it readily applicable to the many complex track layouts encountered in practice. In fact, it is contemplated that the usual embodiment of the invention in actual practice will include crossovers as well as single

switches interconnecting several different tracks providing all kinds of routes, such as alternative and run-around routes, through-routes, and the like.

The operation of each of the track switches is effected by a power operated switch machine SM which can be, for example, of the type shown in the patent to W. K. Howe, Patent No. 1,466,903, dated September 4, 1923. It is to be understood that suitable over-load protection is provided for the switch machine motors such, for example, as is shown in the patent to W. H. Hoppe et al., Patent No. 1,877,876, dated September 20, 1932.

A normally energized polar neutral switch repeater relay WP is provided in the usual manner for repeating the position of each track switch in correspondence with the position of its switch machine SM. For example, the track switch 3 has associated therewith a switch repeater relay 3WP which is energized to operate its polar contacts to a right-hand position when that track switch is locked normal in correspondence with the position of its switch machine 3SM, and such WP relay is energized with its polar contacts operated to a left-hand position when the track switch 3 is locked in a reverse position in correspondence with the position of its switch machine 3SM. The relay 3WP is deenergized whenever the track switch 3 and/or the switch machine SM are unlocked or out of correspondence. Such control of the relay WP for each of the track switches is provided by means of a point detector contact mechanism such, for example, as the mechanism shown in the patent to C. S. Bushnell, Patent No. 1,517,236 dated November 25, 1924.

Signals are provided for governing traffic through the track layout in both directions, signals A, B1, B2, C1, C2, F and G being provided for governing east-bound traffic to the right, and signals D and E being provided for governing west-bound traffic to the left (see Fig. 2). Each of the signals is assumed to be of the search-light type of the general character shown, for example, in the patent to O. S. Field, 1,835,150, dated December 8, 1931; but it is to be understood that other types of signals can as well be used with the system provided by the present invention, such, for example, as semaphore signals, and color light signals having individual color lamp units.

A typical mechanism of one of these search-light signals as employed in the embodiment of this invention has been shown in Fig. 5. This mechanism comprises an optical unit and an electro-magnetic structure for operating the color roundels to their different positions for changing the color indications of the signal, as well as including certain contacts which are operated in accordance with the position of the color roundels. With reference to Fig. 5, a lamp 180 is illustrated as being steadily energized for illuminating the signal, but it is to be understood that approach lighting may be employed if desired. This lamp 180 supplies light through the lens or optical arrangement of the signal, which light must pass through the particular colored roundel then in the center or active position. The roundels indicated in the drawing are green, red and yellow indicated by the letters G, R and Y, respectively, which roundels are on the movable member 181 assuming its biased to normal position with the red roundel R in front of the lamp 180. When the coil 182 of the mechanism

is energized with positive potential on the upper terminal, the electro-magnetic driving structure causes the movable member 181 to rotate clockwise so that the green roundel G is in the active position; and similarly when the upper terminal of the winding 182 is energized with negative potential the movable member 181 is caused to rotate counter clockwise so as to place the yellow roundel Y in the active position.

When the movable member 181 is actuated to place the green roundel G in the active position, the contact 183 is moved to the right, and when the movable member 181 is actuated so as to place the yellow roundel Y in the active position, the contact 184 is moved to the left position. But when the winding 182 is deenergized and the movable member 181 assumes its normal position with the red roundel R in the active position and the contacts 183 and 184 assume their biased to normal positions.

When the movable member 181 is actuated to either energized position, it is apparent that the relay GYP is energized by obvious circuits, but when the member 181 is in its normal position, the relay GYP is always deenergized. In other words, the relay GYP may be conveniently termed a green-yellow indication repeating relay which is energized whenever its associated signal displays either a green or a yellow aspect.

The search-light signals B₁, C₁ and G shown in Fig. 2 and indicated by symbols on the control panel of Fig. 1A are considered to display green, yellow and red indications, but the remaining signals shown in Fig. 2 and indicated in Fig. 1A are assumed to display yellow and red indications. It is to be understood of course that other aspects or indications may be displayed by changing the color of the roundels, or by some suitable arrangement of the signals in combination with other signals, but these aspects or indications have been chosen for convenience in disclosing the invention because green is usually considered a high speed indication for proceed; yellow is usually considered a medium or slow speed indication for proceed; and red is considered a danger or stop indication. Although the typical signal illustrated in Fig. 5 is shown as having all three indications, it is to be understood that the green indication may be omitted for those slow speed signals which do not require such indication, and that the only difference in control is that a reversal of the polarity on the winding 182 is not provided. The control of the winding 182 of the typical circuit of Fig. 5 is shown as provided by a typical signal control relay G, it being understood that each of the signal control relays of Figs. 1A, 1B, 3A and 3B controls its respective signal mechanism.

The track layout for this embodiment of the present invention is divided into track sections 2T and 3T in the usual manner by insulated joints, and track circuits (not shown) are provided in the usual manner for the energization of track relays 2TR and 3TR respectively.

Control machine.—A control machine for use in accordance with the present invention has a control panel upon which is constructed a miniature track diagram as illustrated in Fig. 1A to correspond to the track layout for which the system is provided. Disposed on the track diagram at points corresponding to the signal locations, are entrance and exit buttons NB and XB for the respective entrance and exit points defined by the location of the signals of the track layout. That is, entrance buttons ANB, BNB, CNB, DNB and

ENB are provided for the designation of the signal locations A, B, C, D and E respectively as entrance points. The exit buttons AXB, BXB, CXB, DXB and EXB are provided for designation of the signal locations A, B, C, D and E respectively as exit points.

The button ANB for designation of an entrance point for a route governed by dwarf signal A has an operated position when rotated in a counter-clockwise direction from its normal position. The buttons DNB and ENB for designation of entrance points for routes governed by dwarf signals D and E respectively have operated positions when rotated in a clockwise direction from their normal positions. The buttons BNB and CNB have, in addition to having operated positions provided by counter-clockwise rotation for selecting low speed signals, depressed operated positions are also provided for the selection of high speed signals for governing the entrance to routes. Each of these buttons can also be pulled out from its normal position to cause restoration to normal of the route establishing means for a route originating at that point. The buttons which may be depressed or pulled are biased to their normal positions, but all buttons which have rotated operated positions remain in such positions until restored. The construction of a control button to provide such operated positions can be provided, for example, as shown in the application of J. F. Merkel, Ser. No. 158,720, filed August 12, 1937. Each of the exit buttons XB is a push button of the self-restoring type having a contact closed only when such button is depressed.

Although separate entrance and exit buttons are provided in this embodiment of the present invention for each of the route ends, it is to be understood that a single button for each route end can as well be provided having the required number of distinctive positions for designation of the entrance and exit points for that route end, or a single button for each route end can be provided in combination with circuit means for selecting the desired number of operating conditions responsive to the actuation by an operator of the buttons in a particular sequence.

As an auxiliary means of control for each of the track switches, an auxiliary switch control lever SML is provided on the control panel for each track switch, such lever being useful in attempting to operate its respective track switch to free it of obstructions.

System devices.—An entrance relay NR (see Figs. 1A and 1B) is provided for each of the entrance points, such relay being responsive to the designation of that entrance point by an operator, and being maintained energized until restoration is effective in a manner which will be hereinafter described in detail.

A relay XR is provided for each of the exit points, such relay being energized responsive to the designation of its corresponding exit point where there is an available route extending to that exit point from an entrance point which has been designated. Each exit relay XR is maintained energized, dependent for deenergization upon the restoration of the entrance relay NR for the entrance end of the route having its entrance and exit points designated.

A relay Y is provided for each track switch, such relay being energized in this embodiment of the present invention upon designation of an entrance point, if that track switch can be trialed in a normal position in an available route extend-

ing from such entrance point. Such control for each of the relays Y provides that it can be used under certain conditions for the preselection of the normal or reverse position of its track switch in accordance with a route being established.

Normal and reverse switch control relays N and R are provided for each track switch for causing its respective normal and reverse operation in accordance with each route being established. The N or R relay energized for each track switch in the establishment of a route is maintained energized as long as the route locking for that track switch is effective.

With reference to Fig. 2, normally energized directional stick route locking relays 2ES and 3ES are provided for eastbound traffic, and relays 2WS and 3WS are provided for westbound traffic. Each of the track sections 2T and 3T has a normally energized lock relay L which is controlled in accordance with the route and detector locking, and each of the track switches has a lock stick relay LS which is normally energized, but is dropped away upon the establishment of a route after its track switch has completed its operation to its required position. The use of the route locking relays ES and WS in combination with the lock relays L and LS provides that the track switches can be operated only under safe and desirable conditions.

A polar neutral relay WZ is provided for each of the track switches for governing its operation in accordance with the normal or reverse control selected by the relays N and R for that track switch, such relay WZ providing features generally required in practice, such as a means for reversing its switch machine in midstroke, and insuring the complete operation of its track switch each time operation has been initiated.

The control of each of the search-light signals is governed by a signal control relay G, which is energized for the signal governing entrance to each route when such route is established.

Having thus considered the apparatus provided in this embodiment of the present invention and its general application, the mode of operation and the principles involved will now be considered under various typical operating conditions which would be encountered in practice.

Operation

Normal conditions.—The conditions assumed in this disclosure as being normal are the conditions of the system when there are no routes established, or partially established, no track sections occupied within the interlocking plant, and the signals governing traffic through the track layout are all at danger. The track switches 2 and 3 (see Fig. 2) are shown in their normal positions because it is assumed that the last route established through the track layout required that they be in such positions, as the track switches remain in their last operated positions.

Under normal conditions the relays are all de-energized as illustrated with the exception of the track relays TR (see Fig. 2), the switch repeater relays WP, the lock relays L and LS, the route locking relays ES and WS, and the correspondence relay NCR for each track switch. The relays WP and TR are normally energized by circuits well known to those familiar with the art, and the lock relays for each of the track switches are energized by circuits shown in Fig. 2 of the accompanying drawings.

The route locking relay 2ES is normally en-

ergized by a circuit closed from (+), including back contact 10 of relay AG, back contact 11 of relay B1G, back contact 12 of relay B2G, front contact 13 of relay 2ES, and winding of relay 2ES, to (-). The route locking relay 3ES is normally energized by a circuit closed from (+), including back contact 9 of relay C1G, back contact 14 of relay C2G, front contact 15 of relay 3ES, and winding of relay 3ES, to (-). The route locking relay 3WS is normally energized by a circuit closed from (+), including back contact 16 of relay EG, back contact 17 of relay DG, front contact 18 of relay 3WS, and winding of relay 3WS, to (-). The route locking relay 2WS is normally energized by a circuit closed from (+), including front contact 19 of relay 3WS, front contact 20 of relay 2WS, and winding of relay 2WS, to (-).

The lock relay 2L for track switch 2 is normally energized by a circuit closed from (+), including front contact 21 of relay 2ES, front contact 22 of relay 2TR, front contact 23 of relay 2WS, winding of relay 2L, and front contact 24 of relay 2L, to (-). The lock relay 3L for track switch 3 is normally energized by a circuit closed from (+), including front contact 25 of relay 3ES, front contact 26 of relay 3TR, front contact 27 of relay 3WS, winding of relay 3L, and front contact 28 of relay 3L, to (-). The lock stick relay 3LS for track switch 3 is normally energized by a circuit closed from (+), including front contact 29 of relay 3L, back contact 30 of relay 3WZ, and winding of relay 3LS, to (-). The relay 2LS provided for track switch 2 is energized normally by circuits (not shown) corresponding to circuits provided for the energization of relay 3LS. The normal correspondence relay 3NCR for track switch 3 is normally energized by a circuit closed from (+), including back contact 31 of relay 3R, winding of relay 3NCR, polar contact 32 of relay 3WP in a right hand position, and front contact 33 of relay 3WP, to (-). A correspondence relay 2NCR for track switch 2 is energized by a circuit (not shown) corresponding in character to the circuit described for relay 3NCR.

Route establishing circuit means.—Inasmuch as this invention relates to improvements in the entrance-exit system described in detail in the patent to A. Langdon, Patent No. 2,148,865, dated February 28, 1939, and in the prior application of S. N. Wight, Ser. No. 275,923, filed May 26, 1939, reference may be made to those prior disclosures for a more complete description of the route establishing circuit means and its universal application to complex track layouts in which optional routes and other traffic problems encountered in practice are involved. However, the general mode of operation of the route establishing means of the system as more directly related to the features of the present invention will be pointed out as the description progresses, and will be in part obvious from specific typical examples to be described.

In the establishment of a route, an operator causes the energization of an entrance relay NR for the entrance end of the route to be established by actuation of the entrance button NB associated therewith. If he desires the route to be governed by a low speed signal, such as a call-on or dwarf signal, he rotates the entrance button NB associated therewith in a counterclockwise direction if the signal is for east-bound traffic, and in a clockwise direction if the signal is for west-bound traffic. This causes the energization of an entrance relay associated with

such low speed signal which relay is maintained energized dependent upon the restoration of the associated button from its rotated position. On the other hand, if the route to be established is to be governed by a high speed signal, the designation of the entrance end of such route is effected by the depression of the button NB for the entrance point, such designation being effective to cause the energization of a different entrance relay NR for the high speed signal. When an entrance relay NR is picked up for a high speed signal, it is maintained energized until a train enters the track section in advance or until restoration effected by the pulling out of the associated button.

Responsive to the picking up of an entrance relay NR upon designation of an entrance point, energy is fed through each branch of the initiating circuit network for the direction of traffic designated which corresponds to a route available for use emanating from such entrance point. Energy feeding through such initiating network causes the energization of a route selecting relay Y for each track switch in the track layout that can be included in a predetermined position (generally a normal position) when trailed in an available route emanating from the entrance point having its entrance relay NR energized. The feeding of energy through the various branches of the initiating network corresponding to available routes emanating from each entrance point designated also conditions each of the exit relays for each of the exit points that can be included in an available route extending from the entrance point having its entrance relay NR energized. That is, the picking up of an exit relay XR is dependent upon the designation of that exit point by an operator upon the depression of the exit button XB associated therewith, and is also dependent upon the feeding of energy through the initiating network from the front contacts of an entrance relay NR for the opposite end of an available route extending to that exit point. Inasmuch as the establishment of a route is dependent upon the picking up of an exit relay XR for the exit end of that route, it is believed to be readily apparent, that a route can be established only when it is available because the circuit selections for the control of the exit relay XR for each exit point provide that such relay can be energized only if there is an available route extending from a designated entrance point to that exit point.

Upon the energization of an exit relay XR in the establishment of a route, a completion circuit network is energized to cause the selective energization of normal and reverse relays N and R for each of the respective track switches to correspond with the route being established, such N and R relays having their circuits selected in accordance with the condition of the route selecting relays Y included in the initiating circuit network for the particular direction of the route being established.

Establishment of a route.—To consider as a specific example how the present embodiment follows such general mode of operation in the establishment of a route, assume that an operator desires to set up a route from C to D governed by the low speed signal C2 (see Fig. 2). For designation of an entrance point at signal location C for the clearing of a low speed signal for the route when it is established, an operator rotates the button CNB in a counterclockwise direction, and thus closes operating contacts on 75

the button CNB to cause the picking up of the entrance relay C2NR (see Fig. 1B) by the energization of a circuit closed from (+), including contact 34 of button CNB in a counter clockwise rotated position, back contact 35 of relay C1NR, and winding of relay C2NR, to (—).

Upon the picking up of relay C2NR energy is applied to the initiating network for east bound traffic at front contact 36 to condition the exit relays DXR and EXR for energization upon designation by an operator of an exit point with which either of those exit relays XR is associated. In accordance with the principles as heretofore set forth, the picking up of relay C2NR does not cause the energization of any Y relays as there are no track switches that can be trailed from an entrance point at signal C2.

Upon designation of an exit point for a route by the depression of button DXB, subsequent to the designation of an entrance point at signal C2, the relay DXR is picked up by the energization of a circuit closed from (B—), including front contact 36 of relay C2NR, back contact 37 of relay C1NR, back contact 38 of relay CXR¹, back contact 39 of relay 3N, winding of relay DXR, back contact 40 of relay DNR, and contact 41 of button DXB, closed in a depressed position, to (CN).

Upon the picking up of relay DXR, a stick circuit is closed for that relay from (B—), including front contact 36 of relay C2NR, back contact 37 of relay C1NR, back contact 38 of relay CXR¹, back contact 39 of relay 3N, winding of relay DXR, front contact 42 of relay DXR, and polar contact 170 of relay DXR in a left hand position, to (CN).

In considering the circuits just described for relay DXR it will be noted that the stick circuit for that relay can be closed only if such relay is picked up by energy of a particular polarity applied by the entrance relay C2NR governing entrance to that route, as the opposite polarity would not close polar contact 170 to the left. Thus, the stick circuit for relay DXR is closed only when the entrance relay C2NR is picked up, as the picking up of relay C1NR would apply the opposite polarity upon the closing of front contact 37 of relay C1NR. Such mode of operation is provided because it is assumed that the route over track switch 3 reverse can be governed only by the low speed signal C2. Inasmuch as the switch control relays N and R are maintained energized when a route is established until after restoration has been effected (either by manual control or upon passage of a train in a manner to be hereinafter described), the back contact 39 of relay 3N in the circuit for relay DXR checks that there is no route established in which the normal position of the track switch 3 is called for. Thus, the energization of relay DXR indicates that the establishment of a route including the track switch 3 in a reverse position can be effected.

Upon the picking up of the exit relay DXR, with its polar contacts operated to a left-hand position, the reverse switch control relay 3R is picked up by the energization of a circuit closed from (+), including front contact 43 of relay DXR, polar contact 171 of relay DXR in a left-hand position, upper winding of relay 3R and back contact 44 of relay 3N, to (—). The picking up of relay 3R causes the operation of the track switch 3 to a reverse locked position to establish a route from signal C2 to signal D in a manner which will be hereinafter considered.

when considering the switch control circuits more in detail.

It may be well to point out in passing that even though the relay DXR may be picked up when energized with the polarity selected by the picked up position of relay C1NR, it can neither stick up nor cause the switch control circuits to be energized from front contact 43 of relay DXR by reason of the operation of polar contact 171 to a right-hand position.

Before considering the detail operation of switch and signal control, let us consider a typical example of how a route can be established including the normal position of a track switch, assume that an operator designates an entrance point for signal C2 at a time when a route is available extending from signal C to signal E. The rotation of the button CNB in a counter clockwise direction causes the picking up of relay C2NR in a manner which has been described, and the designation of an exit point for a route extending from signal C2 to signal E by the depression of button EXB causes the picking up of the exit relay EXR by the energization of a circuit closed from (B-), including front contact 36 of relay C2NR, back contact 37 of relay C1NR, back contact 38 of relay CXR¹, back contact 45 of relay 3R, winding of relay EXR, back contact 46 of relay ENR, and contact 47 of button EXB closed in a depressed position, to (CN). The picking up of relay EXR closes a stick circuit for that relay at front contact 48 to shunt contacts 46 and 47 out of the circuit just described.

When relay EXR is picked up in the establishment of a route from signal C2 to signal E, relay 3N is picked up by the energization of a circuit closed from (+), including front contact 49 of relay EXR, upper winding of relay 3N, and back contact 50 of relay 3R, to (-). The picking up of relay 3N causes the operation of the track switch 3 to a corresponding normal position in a manner which will be hereinafter described.

If, in the setting up of the route from C to E as described above, an operator desires the clearing of a high speed signal governing entrance to such route, he designates the entrance point thereto by the depression of button CNB instead of its rotation which has been described. Thus, the depression of button CNB, when the normal conditions of the system exist as they have been described, causes the picking up of the entrance relay C1NR by the energization of a circuit closed from (+), including front contact 51 of relay 3TR, back contact 52 of relay C2NR, contact 53 of button CNB closed in a depressed position, and winding of relay C1NR, to (-). Upon the picking up of that relay a stick circuit is closed to maintain it energized after the button CNB is restored to its normal position from (+), including front contact 51 of relay 3TR, back contact 52 of relay C2NR, contact 53 of button CNB closed both in a depressed and a normal position, front contact 54 of relay C1NR, and winding of relay C1NR, to (-). The picking up of relay C1NR applies energy to the initiating circuit network in an obvious manner at front contact 51, and renders effective the picking up of exit relay EXR upon designation of an exit point at E in a manner similar to that which has been described.

To consider a typical example of the establishment of a route in which a route selecting

relay Y is involved, assume at a time when normal conditions of the system exist as they have been described, that an operator desires to establish a route from signal B to signal C. The designation of an entrance point for such route by the rotation of button BNB in a counter clockwise direction causes the picking up of relay B2NR for defining an entrance point for the low speed signal B2 by the energization of a circuit similar to the circuit described for the picking up of relay C2NR in accordance with the rotation of the button CNB. Upon the picking up of relay B2NR, the relay 2Y is picked up by the energization of a circuit closed from (B-), through a circuit including front contact 55 of relay B2NR, back contact 56 of relay B1NR, back contact 57 of relay BXR, back contact 58 of relay 2R, and winding of relay 2Y, to (CN).

Upon the depression of button CXB for designation of the exit end of the route being established, the exit relay CXR is picked up by the energization of a circuit closed from (B-), including front contact 55 of relay B2NR, back contact 56 of relay B1NR, back contact 57 of relay BXR, back contact 58 of relay 2R, front contact 59 of relay 2Y, winding of relay CXR, wire 60, back contact 61 of relay CXR¹, and contact 62 of button CXB closed in a depressed position, to (CN). The picking up of that relay closes a stick circuit at front contact 63 (see Fig. 1A) to shunt contacts 61 and 62 out of the circuit just described.

Upon the picking up of relay CXR in the establishment of a route from signal B2 to signal C, relay 2N is picked up (because it is selected by the picked up position of the relay 2Y) by the energization of a circuit closed from (+), including front contact 64 of relay CXR, front contact 65 of relay 2Y, upper winding of relay 2N, and back contact 66 of relay 2R, to (-). The picking up of relay 2N causes the operation of the track switch 2 to a normal position in a manner to be hereinafter described more in detail.

If an operator desires a route to be established governed by high speed signal B1, in designation of the entrance end of the route to be established, he depresses the button BNB, and the relay B1NR responds because of the energization of circuits similar to the circuits described for the energization of relay C1NR in accordance with the depression of the button CNB for designation of an entrance point at the high speed signal C1.

Switch control.—In considering the control of the switch machine SM, the description is more particularly directed to the control of the switch machine 3SM as the control of that switch machine is typical of the control provided for switch machine 2SM, and for additional track switches as required in more complex track layouts encountered in practice.

As a typical example of how a track switch is operated to a reverse position from a normal position when the reverse control relay R for that track switch is picked up, assume when track switch 3 is in a normal position, that an operator causes the picking up of relay 3R as has been described in setting up a route from signal C2 to signal D. The picking up of relay 3R under such conditions causes the picking up of the polar neutral relay 3WZ with its polar contacts operated to a left hand position, and the picking up of that relay causes energy to be applied to the control circuit for the switch ma-

chine 3SM to cause the operation of the track switch 3 to its reverse locked position. Upon the picking up of the relay 3R in the setting up of that route, the normal correspondence relay 3NCR is dropped away, and the dropping away of that relay closes a stick circuit for the relay 3LS which maintains that relay energized until the operation of the track switch 3 has been completed, such stick circuit being opened upon the picking up of the reverse correspondence relay 3RCR at that time to cause the relay 3LS to drop away. The dropping away of relay 3LS opens the control circuit for the switch machine 3SM and closes a circuit for the energization of a signal control relay in a manner hereinafter described when considering more specifically the signal controls.

To consider more specifically the circuits providing the above described general mode of operation, the picking up of relay 3R causes the dropping away of relay 3NCR by opening the circuit for that relay at back contact 31. Relay 3WZ is picked up responsive to the picking up of relay 3R with its polar contacts operated to a left hand position in accordance with the energization of a circuit closed from (+), including front contact 31 of relay 3R, and lower winding of relay 3WZ, to (-). The picking up of relay 3WZ causes energy to be applied to the control circuit for the switch machine 3SM to cause its operation to a reverse locked position. The switch control circuit is maintained closed during the operation of the switch machine because relay 3LS is maintained energized during such time by the energization of a circuit closed from (+), including front contact 29 of relay 3L, back contact 69 of relay 3RCR, back contact 70 of relay 3NCR, front contact 71 of relay 3LS, and winding of relay 3LS, to (-). After the operation of the track switch has been completed, the relay 3RCR is picked up by the energization of a circuit closed from (+), including back contact 72 of relay 3N, winding of relay 3RCR, polar contact 32 of relay 3WP in a left hand position, and front contact 33 of relay 3WP, to (-). The picking up of that relay causes the dropping away of relay 3LS by opening the stick circuit for that relay at back contact 69, the normally energized circuit heretofore described for that relay being open at back contact 30 of relay 3WZ. The dropping away of relay 3LS opens the control circuit for the switch machine 3SM in an obvious manner at front contacts 73 and 74 and closes a signal control circuit to be hereinafter described.

To insure the complete operation of the switch machine 3SM, once operation has been initiated, a stick circuit is provided for the relay 3WZ which is closed when relay 3WZ is energized for a reverse control from (+), including back contact 75 of relay 3WP, front contact 76 of relay 3WZ, polar contact 77 of relay 3WZ in a left hand position and lower winding of relay 3WZ, to (-). To further provide that the operation of the track switch would be completed once it has been initiated, a stick circuit is closed during the operation of the track switch for relay 3LS from (+), including front contact 30 of relay 3WZ, back contact 69 of relay 3RCR, back contact 70 of relay 3NCR, front contact 71 of relay 3LS, and winding of relay 3LS, to (-). Such circuit provides that relay 3LS is maintained picked up to close the control circuit for the switch machine 3SM during switch machine operation, even if the lock relay 3L should drop

away during operation of the switch machine. To consider how the track switch 3 is operated to a normal position from a reverse position in accordance with the picking up of the normal switch control relay 3N, as is effected, for example, in setting up a route from signal C1 or C2 to signal E, assume that the ends of such a route have been designated by an operator at a time when the track switch 3 is in a reverse position. The picking up of relay 3N under such conditions causes the dropping away of the correspondence relay 3RCR by the opening of the circuit for that relay at back contact 72, and the picking up of that relay also causes the picking up of relay 3WZ by the energization of an obvious circuit closed at front contact 72 for its upper winding, such energization causing relay 3WZ to be picked up with its polar contacts operated to a right hand position to close the control circuit for switch machine 3SM and thus cause the track switch 3 to be operated to a normal locked position. Relay 3LS is maintained energized during the operation of the switch machine 3SM by stick circuit means as heretofore described, and the completion of operation of the switch machine 3SM is insured by the energization of a stick circuit for relay 3WZ closed from (+), including back contact 75 of relay 3WP, front contact 73 of relay 3WZ, polar contact 77 of relay 3WZ in a right hand position, and upper winding of relay 3WZ, to (-). After the switch machine has completed its operation, the normal correspondence relay 3NCR is picked up by the energization of a circuit which has been described, and the relay 3LS is dropped away by the opening of the stick circuit for that relay at back contact 70 to open the switch machine control circuit and to close the signal control circuit in a manner to be hereinafter described.

As an auxiliary means of switch control, an auxiliary switch control lever 3SML can be actuated to govern the operation of each track switch. For example, the auxiliary switch control lever 3SML, provided for track switch 3, when operated from its center to its upper position, causes the picking up of relay 3R, if the normal conditions of the system exist as they have been described, by the energization of a circuit closed from (+), including contact 78 of lever 3SML in an upper position, center winding of relay 3R, and back contact 79 of relay 3N, to (-). The picking up of relay 3R due to such energization causes the operation of the switch machine 3SM to a reverse position in accordance with the same mode of operation which has been described when assuming relay 3R to be picked up responsive to route control as designated by the actuation of entrance and exit buttons by an operator.

If an operator desires to cause the operation of the track switch 3 to a normal position by auxiliary control, he actuates the lever 3SML to a lower normal operating position, and relay 3N responds to such operation because of the energization of a circuit closed from (+), including contact 78 of lever 3SML, closed in a lower operating position, center winding of relay 3N, and back contact 80 of relay 3R, to (-). The picking up of relay 3N causes the operation of the switch machine 3SM to a normal position in accordance with the same mode of operation which has been described when the relay 3N is energized in response to the designation by an oper-

ator of entrance and exit points of a route including the switch 3 in a normal position.

Signal controls.—Each of the search-light signals for the track layout of Fig. 2 is governed in accordance with the energization and deenergization of a signal control relay G which is energized over a signal control circuit network selected by the switch control relays of the route establishing means shown in Figs. 1A and 1B. A single circuit network is provided for this purpose to effect the energization of the relays G for signals governing traffic in both directions, and the relay G for any particular signal can be energized only after the route which it is to govern has been completely established and the track switches included therein have become locked.

It has been explained above how a route may be established from signal location C to signal location D by the rotation of the entrance button CNB and the momentary actuation of the exit button DXB. After the track switch 3 has operated to a reverse locked position into correspondence with its control by the relay 3R, the relay 3LS is deenergized (see Fig. 2) as above described. This closes the signal control circuit network so that the signal control relay C2G is energized from (+), over a circuit including polar contact 172 of relay DXR in a left-hand position, front contact 81 of relay DXR, back contact 82 of relay 3NCR, front contact 83 of relay 3RCR, back contact 84 of relay 3LS, back contact 85 of relay CXR¹, front contact 86 of relay C2NR, winding of relay C2G, to (-).

This energization of the relay C2G closes front contacts 185 and 186 to energize its associated signal mechanism C2 with such a polarity as to cause that signal to actuate its yellow roundel Y to an active position and display a slow speed or call-on signal aspect.

It may be noted that any accidental manipulation on the part of the operator which might result in the picking up of the relay C1NR in response to the depression of the button CNB followed by the actuation of the exit button DXB could not possibly cause the clearing of the signal C1 instead of the signal C2. In the first place, as pointed out above the actuation of the polar contacts of the relay DXR to right-hand positions fails to close polar contact 171 in a left-hand position so that the route would not be established. In the second place, the polar contact 172 would be in a right-hand position so that the signal control relay C1G could not receive energy even though the front contact 89 of the entrance relay C1NR might be closed.

In setting up a route from C to E, the operator may cause either the high speed signal C1 or the low speed signal C2 to be cleared at his discretion and dependent upon the characteristic operation of the entrance button CNB.

If, for example, the operator rotates the entrance button CNB in a counterclockwise direction followed by the actuation of the exit button EXB to effect the response of the route establishing means as above described, a circuit is closed for the relay C2G from (+), through a circuit including front contact 91 of relay EXR, front contact 92 of relay 3CNR, back contact 83 of relay 3RCR, back contact 84 of relay LS, back contact 92 of relay CNCR, back contact 83 of relay C2NR, windings of relay C2G, to (-).

The picking up of the relay C2G closes front contacts 185 and 186 to so energize its associated signal mechanism C2 with a polarity to cause

the signal C2 to display a low speed signal aspect.

If, on the other hand, the operator had desired to clear the high speed signal C1, he would have depressed the entrance button CNB (instead of rotating it in a counterclockwise direction) which would have resulted in the picking up of the entrance relay C1NR in a manner above described. This would place positive potential from (B+) on the initiating network so that the actuation of the exit button EXB would cause the exit relay EXR to be picked up and close its stick circuit. The relay EXR then energizes the completion network, as above described, to establish the route.

When the route is properly established, and providing the track section 3T is unoccupied, the signal control relay C1G is energized by a circuit closed from (+), including front contact 91 of relay EXR, front contact 92 of relay 3NCR, back contact 83 of relay 3RCR, back contact 84 of relay 3LS, back contact 85 of relay CXR¹, front contact 88 of track relay 3TR, front contact 89 of entrance relay C1NR, windings of relay C1G, to (-).

The signal mechanism of signal C1 is controlled not only by its signal control relay C1G but its energizing circuit is also energized with one polarity or the other in accordance with the clear or stop indication of the next signal in advance governing traffic in the same direction. In other words, the signal G, when at stop, causes its associated green-yellow indication relay GGYP to be deenergized, but when displaying a yellow or a green proceed indication, such relay is energized, which in turn governs signal C1 accordingly.

If the signal G is at stop, then the picking up of the signal control relay C1G causes positive potential to be applied to the signal mechanism of signal C1 from (+), through a circuit including back contact 187 of relay GGYP, back contact 189 of relay 3RCR, front contact 190 of relay C1G, signal mechanism for signal C1, front contact 191 of relay C1G, front contact 192 of relay 3RCR, back contact 194 of relay GGYP, to (-). Thus, the signal C1 is energized with such a polarity that its movable member actuates the yellow roundel Y into an active position to cause such signal to display a caution signal aspect, namely, approach the next signal prepared to stop.

If, on the other hand, the signal G is cleared, then the relay GGYP is energized and contacts 187 and 194 causes the polarity of energization of the signal mechanism for signal C1 to be reversed to thereby cause the green roundel G to be moved to an active position so that the signal C1 displays a high speed proceed aspect. It should be understood that signal G may be another manually controlled signal of another interlocked group, or may be a signal governing automatic signal territory.

Thus, it is evident that the system of the present invention requires manipulations on the part of the operator to not only designate the entrance and exit ends of the desired route but to also designate the entrance end in a manner characteristic of the class of signal which is to govern that route. If a route is to allow only slow speed traffic, then the signal at the entrance to that route can be cleared only when the operator designates that signal location as an entrance point in a manner characteristic of a slow speed signal. If some route may have either high

speed or slow speed traffic, then the operator may optionally determine whether a slow speed or a high speed signal indication shall be given by the manner in which he actuates the entrance button with the limitation that the high speed signal shall be controlled in accordance with traffic conditions so as to give its high speed indication only providing the next signal in advance is clear and traffic is such that the train can proceed in accordance with such high speed signal aspect.

It is believed from the typical examples which have been described that it will be readily apparent how the signal control circuit network is organized to provide control for each of the signal control relays G, and how such organization can be modified to fit any particular track layout encountered in practice.

Route locking.—The use of the entrance-exit system provided by the present invention in the governing of complex track layouts requires the use of route locking which can be provided in accordance with the requirements of practice. One form of route locking which seems to be preferred in many cases for use with entrance-exit types of systems is that in which normally energized directional stick relays are provided for the track section and are governed by an arrangement of circuits which provides that the route locking relays for the particular direction for which a route is established are dropped away for the track sections included in the established route in advance of a train, and such relays are again picked up as the train progresses through the route upon the energization of the respective track relays for the track sections in the rear of such train. Such an organization provides what is generally known in practice as "sectional release route locking."

Although the simple track layout used for this embodiment of the present invention does not require the full quota of directional stick route locking relays that would be required for each track circuit in a complex track layout, a directional stick relay ES and a directional stick relay WS for respective east and west bound traffic is provided for each track section as a typical example of how such route locking relays would be provided in more complex track layouts. Thus, the route locking relays 2ES and 3ES (see Fig. 2) are provided for respective track sections 2T and 3T for east bound traffic, and the directional stick relays 2WS and 3WS are provided for the respective track sections 2T and 3T for west bound traffic.

Upon the establishment of a route from signal location C to signal location D, as has been described, the picking up of signal control relay C2G causes the dropping away of the route locking relay 3ES by opening the circuit for that relay at back contact 14, and the dropping away of relay 3ES causes the dropping away of the lock relay 3L for track switch 3 by opening the circuit for that relay at front contact 25. The dropping away of relay 3L, under such conditions, causes the establishment of a stick circuit for relay 3R (which is picked up at that time) closed from (+), including back contact 93 of relay 3L, front contact 94 of relay 3R, center winding of relay 3R, and back contact 79 of relay 3N, to (-). Such stick circuit is closed to maintain relay 3R picked up as long as the track switch 3 is locked by the route locking in order to prevent the so-called "preconditioning of routes." That is, with reference to Fig. 1B the picked up position of relay

3R by opening back contact 45 prevents the picking up of the exit relay EXR if an operator attempts to establish a conflicting route which requires the track switch 3 to be in a normal position by the opening of back contact 45. It is also of course provided that the dropping away of the lock relay 3L prevents the application of energy to the control circuit for the switch machine 3SM by opening the circuit for the lock relay 3LS at front contact 29. In more complex track layouts where more than one track switch is included in the route, the dropping away of the route locking relay ES or WS for the track switch nearest the signal governing entrance to such route causes the route locking relays for that direction of traffic to be successively deenergized for the other track switches included in the route. For a more detailed description of how such general mode of operation is provided, reference can be made to the patent to A. Langdon, Patent No. 2,148,865, dated February 28, 1939, and if approach locking is to be provided as well, the circuits for the directional stick relays can be provided, for example, as shown in the patent to C. F. Stoltz, Patent No. 2,115,511, dated April 26, 1938.

After a train has left the track section for which a route locking relay is deenergized, such route locking relay is picked up. For example, the passage of a train through the route from signal C2 to signal D allows the picking up of relay 3ES responsive to the picking up of the track relay 3TR in accordance with the general restoration procedure as hereinafter described.

Restoration to normal.—The restoration to normal of parts of the system associated with the establishment of each route, and the restoration to stop of the signal governing entrance to such route can be effected either by the manual actuation of the entrance button NB for entrance to such route, or, in the case of stick signals and semi-automatic high speed signals, upon the entrance of a train into the route established.

To consider how manual restoration to normal is effected, assume, for example, that an operator has caused the establishment of a route from signal C to signal E, such route being governed by the low speed signal C2. To cause that signal to be restored to stop, and the parts of the system associated with the establishment of that route to be restored to normal, with the route unoccupied by a train, an operator rotates the entrance button CNB (see Fig. 1A) in a clockwise direction back to its normal position. Such rotation causes the dropping away of relay C2NR (see Fig. 1B) by opening the circuit for that relay at contact 34 of button CNB, and the dropping away of that relay causes the signal control relay C2G which governs the low speed signal C2 to be dropped away by opening the circuit for that relay at front contact 86. The deenergization of the search light signal C2 causes such signal to display a red stop indication.

The dropping away of relay C2G causes the picking up of the lock relay 3ES (see Fig. 2) by the energization of a circuit closed from (+), including back contact 9 of relay C1G, back contact 14 of relay C2G, front contact 95 of relay 3TR, and winding of relay 3ES, to (-). When relay 3ES is picked up, a stick circuit which has been described is established for that relay to maintain it energized upon passage of a west bound train through track section 3T. The relay 3L is picked up upon the energization of relay 3ES by the energization of a circuit closed from

(+), including front contact 25 of relay 3ES, front contact 26 of relay 3TR, front contact 27 of relay 3WS, winding of relay 3L, and contact 97 of lever 3SML closed when such lever is in its center position, to (-). When relay 3L is picked up, a stick circuit is established for that relay as has been heretofore described.

The dropping away of relay C2NR, responsive to restoration designation by an operator, causes the dropping away of the exit relay EXR for the route established by the opening of the circuit for that relay at front contact 36 (see Fig. 1B), and such relay in dropping away effects the release of relay 3N by opening the pick-up circuit for that relay at front contact 49. The stick circuit for the center winding of relay 3N is opened upon the picking up of relay 3L (see Fig. 2) at back contact 93. The dropping away of relay 3N causes the dropping away of the polar neutral switch control relay 3WZ by opening the circuit for that relay at front contact 72. When relay 3WZ is dropped away, a circuit is closed to cause the picking up of the lock relay 3LS from (+), including front contact 29 of relay 3L, back contact 30 of relay 3WZ, and winding of relay 3LS, to (-), thus completing restoration to normal of the parts of the system associated with the setting up of a route from signal C2 to signal E.

If an operator wishes to cause the restoration to normal of the signal C1 when it governs an established route from C to E, such restoration is effected in a manner similar to that described except that it is initiated by the pulling out of button CNB to open contact 53 in the stick circuit for relay C1NR, which in turn effects the restoration of the system by opening front contacts 37 and 89.

To consider a typical example of how automatic restoration can be effective for a route upon passage of a train, assume that the signal C1 is cleared for a route established as has been described from signal C to signal E, and assume an approaching train to accept signal C1 and enter track section 3T. The dropping away of relay 3TR causes the dropping away of the entrance relay C1NR by opening the circuit for that relay at front contact 51 (see Fig. 1B), and the dropping away of relay C1NR under such conditions causes the restoration to normal of parts of the system associated with the established route from signal C1 to signal E in a manner similar to that which has been described except that the restoration of the route locking is effective only after the passing train has left track section 3T, and thus the relay 3L (see Fig. 2) can only be picked up after the train has left that route. Inasmuch as the restoration of the relay 3N is dependent upon the release of the stick circuit for that relay upon the picking up of relay 3L, the restoration to normal of the relays 3N, 3WZ and 3LS does not become effective until relay 3L has been picked up after the restoration of the route locking for that route.

Through route control.—Although it is proposed in accordance with the present invention to provide an entrance-exit type of interlocking system which includes the facility of through route control, it is proposed that such through route control shall be limited to routes which provide for high speed train movements and that manipulations for such through route control shall be characteristic of such high speed signals. This is because of the different kinds of

train movements which are made with the different governing signals.

More specifically, low speed signals, such as dwarf and call-on signals, are used mostly for switching purposes to connect one train with another, to run a train into a dead end siding, to run a second train into a station platform or a track section which is already occupied by a first train, and such other low speed train movements which require that the switches of a route be in proper positions and locked but in which it is unnecessary for automatic track circuit control to be included for the rear end protection of trains. Any low speed signal of this type can of course be cleared only when the route which it governs is completely established and no signal for the opposing direction is also cleared. Thus, the clearing of a low speed signal, such as a dwarf or a call-on, conveys to a trainman an indication that the route in advance is established, but that he must be prepared to stop on sight of a train or other obstruction in advance.

It is therefore very desirable that the clearing of a low speed signal by an operator should be effected with great care and with the understanding that responsibility for safe train movement has been shifted from the automatic signalling system to the train crew and the operator. Such being the case, it is desirable that a distinctive operation be required for each low speed signal which is to be cleared, and that under no circumstance should a low speed signal be cleared by through route control.

It is proposed in accordance with the present invention to provide an entrance-exit type of interlocking system to accomplish the above mentioned object and at the same time organize the system so that an intermediate high speed signal cannot inadvertently be cleared when the operator has designated the entrance point as governed by a low speed signal. In other words, a signal location may be designated as an entrance point to be governed by a low speed signal but the operator instead of designating an exit point within the same interlocked group might inadvertently designate an exit point in some succeeding interlocked group which would be the exit end of some through route originating at the designated entrance point. Under such circumstances, certain prior entrance-exit interlocking systems would effect the clearing of the low speed signal for the entrance point designated and also the clearing of the signals for the various intermediate signal locations in the through route. However, the present invention is organized to prevent such operation in response to such manipulation and the high speed intermediate signals may be cleared in response to through route manipulations only providing the entrance point has been designated in a manner characteristic of a high speed signal.

This is accomplished in the embodiment of the present invention by so controlling the through route connections which inter-relate the initiating circuit networks for adjacent interlocked groups, that these inter-connections are closed for available through routes only under circumstances where it is desired that a high speed through route be established.

More specifically, if an operator designates an entrance point for the clearing of a high speed signal by the depression of the entrance button NB for that entrance signal location, a particular polarity is applied to the initiating circuits

for the routes originating at that point, which energy causes the energization of a polar neutral relay NP for each signal which may become an intermediate signal in an available through route originating at the designated entrance point. The energization of such entrance repeating relay NP for a signal location closes the through route connection at that signal location and energizes the initiating circuits of the next interlocked group for the routes originating at such intermediate signal location. Thus, the initiating circuits for each of the interlocked groups forming a part of the through routes originating at the designated entrance point are properly conditioned to effect the preselection of the positions of the switches in such through routes in readiness for the designation of the exit point of a particular one of such available through routes.

However, if an operator designates an entrance point by the rotation of the entrance button for that particular signal location to control a low speed signal thereat, the opposite polarity is applied to the initiating circuits for the routes originating at that signal location which causes the polar neutral relays NP for the signal locations at the ends of the routes within that interlocked group to be so energized that the through route connections are opened, and the only exit relays which are conditioned to be responsive to exit designation are those within the same interlocked group in which the entrance point has been designated.

As an example of such general mode of operation, the designation of an entrance point for the clearing of the high speed signal B1 (see Fig. 1A) causes the energization of the entrance relay B1NR, which, in picking up, applies (B+) energy to the initiating network for the energization of the relay 2Y. Upon the picking up of relay 2Y, the polar neutral relay NP is picked up with its polar contacts operated to a right hand position, and such energization causes a through route connection to be established between the initiating networks for the two adjacent track portions for east bound traffic. Thus, energy feeds through both initiating networks from the source as applied at front contact 56 of the entrance relay B1NR, and so conditions the relays for each of the exit points that the designation of an exit point by the depression of either of buttons CXB or EXB causes the establishment of a route extending to that exit point. It is thus provided, by the application of that particular polarity to the initiating networks, that a through route can be set up from signal B1 to the exit point at E, when such exit point is designated by an operator upon depression of exit button EXB. However, if the designation of an entrance point for a route governed by the low speed signal B2 is effected by the rotation of the button BNB, the opposite polarity is applied to the initiating network, and energy feeds through such network to cause the picking up of the relay 2Y and the conditioning of the relay CXR for energization, but the polar neutral relay CNP is picked up with its polar contacts operated to a left hand position to maintain open the through route connection between the adjacent track portions at the intermediate signal location, and thus render the designation of either of exit points D or E upon the depression of the button XB for such point ineffective for causing the establishment of a through route.

To more specifically point out how such mode of operation is effective, assume, as a typical example, that an operator desires to establish by end-to-end control a through route extending

- 5 from the high speed signal B1 to an exit point at signal E. To designate signal location B as the entrance point for such route, the operator depresses the button BNB to close the pick-up circuit of relay B1NR from (+), including front contact 205 of relay 2TR, back contact 206 of relay B2NR, actuated contact 207 of button BNB, windings of relay B1NR, to (-). The picking up of the relay B1NR closes front contact 208 which shunts out the actuated button contact 207 of button BNB so as to render the relay B1NR dependent for energization upon front contact 205 of relay 2TR and upon the normally closed contact 207 which may be opened by pulling out the button BNB. The picking up of that
- 10 relay B1NR causes the picking up of relay 2Y in accordance with (B+) energy applied at front contact 56, and the picking up of relay 2Y closes a circuit for the energization of the polar neutral relay CNP from (B+), including front contact 56 of relay B1NR, back contact 57 of relay BXR, back contact 58 of relay 2R, front contact 59 of relay 2Y, and winding of relay CNP, to (CN). When relay CNP is picked up due to such energization its polar contacts are
- 15 operated to a right hand position and a through route connection is closed to condition each of the relays DXR and EXR (see Fig. 1B) for energization upon the designation by an operator of the exit point with which such relay is associated.

Thus, if an operator depresses the exit button EXB for designation of an exit point in the establishment of a through route by end-to-end control, the relay EXR (see Fig. 1B) is picked up

- 20 by the energization of a circuit closed from (B+), including front contact 56 of relay B1NR (see Fig. 1A), back contact 57 of relay BXR, back contact 58 of relay 2R, front contact 59 of relay 2Y, front contact 98 of relay CNP, polar contact 99 of relay CNP in a right hand position, back contact 100 of relay CXR, wire 101, back contact 36 of relay C2NR, back contact 37 of relay C1NR, back contact 38 of relay CXR¹, back contact 45 of relay 3R, winding of relay EXR, back contact 46 of relay ENR, and contact 47 of button EXB closed in a depressed position, to CN. The picking up of relay EXR closes a stick circuit for that relay at front contact 48 to shunt contacts 46 and 47 out of the circuit just described.

25 Assuming the relay EXR to have been picked up in the establishment of a route by end-to-end control from signal B1 to signal G, the relay 3N is picked up by the energization of a circuit which has been described, and the picking up of that

- 30 relay causes the picking up of the through route relay CXR by the energization of a circuit closed from (+), including front contact 49 of relay EXR, front contact 102 of relay 3N, winding of relay CXR, back contact 103 of relay C2NR, and back contact 104 of relay C1NR, to (-). The picking up of that relay closes a stick circuit for shunting contacts 103 and 104 out of the circuit just described, from (+), including front contact 49 of relay EXR, front contact 102 of relay

- 35 3N, winding of relay CXR, front contact 105 of relay CXR, wire 106, and back contact 107 of relay CXR, to (-).
- 40 When relay CXR is picked up, in setting up a route by end-to-end control, a circuit is closed to cause the picking up of relay C1NR from (+), in-

- 45

cluding front contact 51 of relay 3TR (see Fig. 1B), back contact 52 of relay C2NR, contact 53 of button CNB in a normal position, front contact 108 of relay CXR, and winding of relay C1NR, to (-). When relay C1NR is picked up, a circuit is closed to cause the picking up of the exit relay CXR for the route extending through the adjacent track portion by the energization of a circuit closed from (B+), including front contact 56 of relay B1NR (see Fig. 1A), back contact 57 of relay BXR, back contact 58 of relay 2R, front contact 59 of relay 2Y, winding of relay CXR, wire 60, back contact 61 of relay CXR¹, front contact 109 of relay CXP, and front contact 110 of relay C1NR, to CN. The picking up of relay CXR causes the dropping away of relay CXP by opening the stick circuit for that relay at back contact 107, the pick-up circuit for relay CXP having been opened upon the picking up of relay C1NR. That relay is made slow enough in dropping away to allow time for the establishment of a stick circuit for relay CXR, which is closed at front contact 63 to shunt contacts 61, 109 and 110 out of the pick-up circuit for that relay.

Responsive to the picking up of relay CXR, the relay 2N is picked up by the energization of a circuit which has been described, and the picking up of that relay completes the selection of the through route extending from signal B1 to the exit point at signal E. After the track switch included in the route extending through each of the track portions has been properly positioned in accordance with the energization of the relay N for that track switch, the lock relay LS for that track switch is dropped away to cause the energization of the signal control relay for the signal governing entrance to such track portion in accordance with circuits heretofore described in considering in detail the signal controls provided.

More specifically, the dropping away of the lock stick relay 3LS after the track switch 3 has properly assumed its normal position, causes the energization of the signal control relay C1G which in turn causes the energization of the signal mechanism C1. The signal mechanism C1 is energized with one polarity or the other depending upon whether the signal G is clear or stop so that the signal C1 indicates yellow or green respectively depending upon such conditions. As noted above, the signal G may be the entering signal of another interlocked group and manually controlled by means provided in accordance with the present invention, or, as assumed for purposes of this disclosure, such signal G may be the entering signal of automatic block 35 signalling territory and automatically controlled in accordance with traffic conditions in advance.

Also, the dropping away of the lock stick relay 2LS after the track switch 2 has properly operated to a normal position, effects the energization of the signal control relay B1G by a circuit closed from (+), including front contact 137 of relay CXR, contact 135 of relay 2LS, back contact 134 of relay 2RCR, front contact 133 of relay 2NCR, back contact 132 of relay BXR, front contact 195 of relay 2TR, front contact 196 of relay B1NR, windings of relay B1G, to (-). The energization of the signal control relay B1G closes front contacts 197 and 198 so that the signal mechanism of signal B1 is energized with one polarity or the other depending upon whether the contacts 199 and 200 of relay C1GYP are dropped away or picked up. If the relay C1GYP is dropped away the signal mechanism B1 is energized with such a polarity as to move its yellow roundel Y

into an active position causing the signal B1 to give a medium speed aspect. On the other hand, if the relay C1GYP is energized, the opposite polarity is supplied to the signal mechanism B1 so that the green roundel G is moved to an active position causing such signal to display a high speed aspect. It is, of course, understood that the relay C1GYP is controlled in accordance with the condition of the signal mechanism C1 as typically illustrated in Fig. 5.

Thus, in the particular case under consideration where the signal C1 assumes a condition to display either of caution aspect or a high speed aspect, as above described, the relay C1GYP is energized so that the signal B1 is caused to give a high speed aspect.

Upon the picking up of relay CXR in the establishment of the through route just described, the through route connection between the initiating networks for the adjacent track portions is opened at back contact 100, and the initiating network for the track portion having signal C1 as an entrance point is energized in accordance with the picked up position of relay C1NR at front contact 37 with the proper polarity used in connection with the clearing of high speed signals. In order that the initiating circuit will not be deenergized upon the shifting of contact 37 of relay C1NR, front contact 111 of relay CXP shunts around contacts 36 and 37 of relay C2NR and C1NR to maintain the through route connection closed while either of such contacts is being shifted in the setting up of a route by end-to-end control. When the through route connections are opened at each of the intermediate signals in the establishment of a route by end-to-end control, it is believed apparent that the route establishing means for each of the interlocked groups is then in the same condition as would be effected if the route included in each of such interlocked groups forming a part of the whole through route had been set up in accordance with the designation by an operator of the respective entrance and exit ends of its own interlocked group. Such being the case, it should be apparent that the manual and automatic restoration to normal of the route establishing means is effected in the same manner for each interlocked group, as has been described, the restoration for each interlocked group being independent of the restoration for the adjacent interlocked group.

Single intermediate signal.—With reference to the track layout of Fig. 2, it will be seen that the signal location C provides signals for governing only east-bound traffic and that west-bound traffic is governed through the track layout by signals D and E. It will thus be readily understood that the route establishing means for the two interlocked groups must be so interrelated that no route can be established from E to B if a route is established from B to C; also, that any route established from E to B should not be interrupted by any manipulation of the buttons CNB or CXB. To accomplish this, a special interlock is provided between the initiating circuits for opposite directions at this intermediate signal location C by the provision of what might conveniently be termed "a phantom exit relay." In other words, a relay CXR¹ is provided at the signal location C which is picked up when an entrance point is designated at either E or D without requiring an exit designation for the signal location C, and this relay simulates an exit condition at this signal location against

which the initiating circuits for the opposite direction can be interlocked. This relay CXR¹ (see Fig. 1B) has its pick-up circuit controlled so as to check the deenergized condition of the entrance and exit relays at that intermediate signal location and includes certain of its own contacts in the initiating circuit for the opposite direction as well as the pick-up circuit for the exit relay CXR so as to prevent any route from being established in such opposite direction.

More specifically, in the setting up of a route for west bound traffic from signal E to an exit point at signal B, the energization of the entrance relay ENR responsive to entrance designation for the route to be established causes the picking up of relay 3Y by the energization of a circuit closed from (+), including front contact 112 of relay ENR, back contact 113 of relay EXR, back contact 114 of relay 3R, and winding of relay 3Y, to (-); and the picking up of that relay causes the picking up of relay CXR¹ by the energization of a circuit closed from (+), including front contact 112 of relay ENR (see Fig. 1B), back contact 113 of relay EXR, back contact 114 of relay 3R, front contact 115 to relay 3Y, winding of relay CXR¹, back contact 116 of relay C1NR, back contact 117 of relay C2NR, wire 118, and back contact 119 of relay CXR, to (-). The picking up of relay CXR¹ closes a stick circuit at front contact 120 to shunt contacts 116, 117 and 119 out of the circuit just described.

When relay CXR¹ is picked up, a circuit is closed to condition each of the exit relays AXR and BXR so that it may be picked up upon designation of the exit point with which that relay is associated, if there is an available route extending from the entrance point which has been designated.

Upon depression of the button BXB for designation of an exit point, relay BXR is picked up by the energization of a circuit closed from (+), including front contact 112 of relay ENR (see Fig. 1B), back contact 113 of relay EXR, back contact 114 of relay 3R, front contact 115 of relay 3Y, front contact 121 of relay CXR¹, wire 122, back contact 123 of relay 2R, winding of relay BXR, back contact 124 of relay B1NR, back contact 125 of relay B2NR, and contact 126 of button BXB closed in a depressed position, to (-). The picking up of relay BXR closes a stick circuit for that relay at front contact 127 to shunt contacts 124, 125 and 126 out of the circuit just described.

The response of relay BXR causes the picking up of the relay 2N by the energization of a circuit closed from (+), including front contact 128 of relay BXR, lower winding of relay 2N, and back contact 66 of relay 2R, to (-). Upon the picking up of relay 2N a circuit is closed to cause the picking up of relay 3N in accordance with the picked up position of the relay 3Y, from (+), including front contact 128 of relay BXR, front contact 129 of relay 2N, wire 130, front contact 131 of relay 3Y, lower winding of relay 3N, and back contact 50 of relay 3R, to (-).

After the track switches have responded in accordance with the energization of the relays 2N and 3N, a signal control circuit is closed upon the dropping away of relays 2LS and 3LS to cause the picking up of the relay EG, from (+), including front contact 132 of relay BXR (see Fig. 1A), front contact 133 of relay 2NCR, back contact 134 of relay 2RCR, back contact 135 of relay 2LS, back contact 137 of relay CXR, wire 75

138, front contact 85 of relay CXR¹, back contact 84 of relay 3LS, back contact 83 of relay 3RCR, front contact 92 of relay 3NCR, back contact 91 of relay EXR, front contact 139 of relay ENR, and winding of relay EG, to (-). The picking up of relay EG causes energy of the proper polarity to be applied to the search light signal E for causing that signal to give a yellow or slow speed indication.

10 With the route established from E to B and the signal E cleared, it is noted that the relay CXR¹ is maintained energized dependent upon the entrance relay ENR, and when picked up opens contacts 38 and 61 as well as back contact 85. 15 The opening of back contact 38 prevents the entrance relays C1NR and C2NR from applying potential to the initiating circuit for the opposite direction. In this connection, it is noted that there is no interlocking contacts to prevent the 20 relays C1NR or C2NR from being energized at any time that their respective control button contacts are closed. However, should the relay C1NR, for example, be picked up opening back contact 116, such inadvertent energization of this 25 relay while the route from E to B is established does not deenergize the relay CXR¹ because the stick contact 129 shunts out the interlocking contact 116. Also, the opening of back contact 85 prevents energy in the signal control network 30 from being passed to either the relays C1G or C2G. The open condition of back contact 61 obviously prevents the picking up of the relay CXR.

In view of the fact that the initiating network control for this route from E to B is entirely dependent upon the picked up condition of the relay ENR, it will be entirely obvious that the restoration of the entrance button ENB to its normal position will restore the signal E to stop and allow the route establishing means to assume a 40 normal condition.

It will be noted that the initiating network of the route establishing means for setting up routes and clearing signals for west-bound traffic is not polarized. This is due to the fact that the track 45 layout chosen for the embodiment of the present invention only has the low speed signals D and E governing west-bound traffic and there are no intermediate signals for through route control involved in such west-bound traffic movements.

50 Thus, it has been unnecessary to make the relays AXR and BXR of the polar neutral type as shown for the relay DXR. However, it is to be understood that the principles of the invention shown for governing east-bound traffic may also 55 be applied to the means employed for governing west-bound traffic, which would probably be required in an installation of any appreciable size and complexity of track layout where many double intermediate signal locations would be found 60 requiring both initiating networks to be similarly controlled.

Route establishing circuit means adapted to foreign practice.—As mentioned above, the principles of the present invention may be applied to 65 means which is readily adaptable to provide signalling in accordance with the practices of various foreign railroads. To accomplish a disclosure of such adaptation, the route establishing means of Figs. 1A and 1B have been modified as shown in Figs. 3A and 3B with the corresponding relays and contacts being identified by the same reference characters. It is also to be understood that the route establishing means of Figs. 3A and 3B is to be used with the track layout and typical circuits shown in Fig. 2, the only difference being

that the high speed signal C1 is eliminated entirely and only a shunt signal is considered to be located at this intermediate signal location. This has been indicated on the control panel by showing the low speed signal symbol C, and such low speed shunt signal is considered to be at the corresponding point of the track layout in Fig. 2. Also, the route locking shown in Fig. 2 is required to be modified as shown in Fig. 4 for reasons hereinafter pointed out in detail. Other differences will be pointed out as the description of this modified form of the invention progresses.

With reference to Fig. 3A, in accordance with foreign practice, the signals A, B2, C, D, E and F are low speed or shunting signals used primarily for switching movements, and the signals B1 and G are running or high speed signals which can be cleared only when there is an available route extending to the next running signal. That is, if an operator wishes to set up a route for a train from signal B1 to signal E, for example, the actuation of the respective entrance and exit control buttons for the ends of that route cause its establishment, and, in accordance with foreign signal practice, a train accepting the entering running signal B1 proceeds past the shunt signal C which remains at stop.

If, however, an operator wishes to set up a route from signal B2 to signal E by the clearing of shunt signals for governing passage through such route, he cannot cause such route to be established by the actuation of the respective entrance and exit buttons BNB and EXB only, but he must actuate the entrance and exit buttons for each of the respective track portions or interlocked groups involved in the route. That is, a route governed by a shunt signal cannot be established by end-to-end or through route control.

To consider the establishment of a route for clearing a running signal, assume that an operator designates an entrance point for the route from signal B to signal E (see Fig. 3A) by the depression of the button BNB. This closes a pick-up circuit for the relay B1NR from (+), including front contact 205 of relay 2TR, back contact 206 of relay B2NR, actuated contact 207 of button BNB, windings of relay B1NR, to (-). As soon as the relay B1NR picks up, it closes front contact 208 to shunt out the actuated button contact 207 so that the relay B1NR is then maintained energized dependent upon front contact 205 of the track relay 2R although the operator releases the button BNB. It is understood that the operator may release the relay by pulling the button BNB to open the normally closed contact 207. The picking up of relay B1NR causes the picking up respectively of the relays 2Y and CNP by the energization of circuits corresponding to circuits which have been described. The picking up of relay CNP conditions the relay EXR (see Fig. 3B) for energization when the exit point with which such relay is associated is designated. Thus, the depression of the button EXB for designation of the exit point at signal E causes the picking up of relay EXR by the energization of a circuit closed from (B+) including front contact 56 of relay B1NR (see Fig. 3A), back contact 57 of relay BXR, back contact 58 of relay 2R, front contact 59 of relay 2Y, front contact 98 of relay CNP, polar contact 99 of relay CNP in a right hand position, wire 101, back contact 36 of relay CNR, back contact 38 of relay CXR¹, back contact 45 of relay 3R, winding of relay EXR, back contact 46 of relay ENR, and contact 47 of button

EXB closed in a depressed position to (CN). The picking up of relay EXR closes a stick circuit at front contact 48 to shunt contacts 46 and 47 out of the circuit just described.

Responsive to the picking up of relay EXR, the relay 3N is picked up by the energization of a circuit which has been described, and the picking up of that relay causes the picking up of relay CXP by closing a circuit for that relay from (+), including front contact 49 of relay EXR (see Fig. 3B), front contact 103 of relay 3N, winding of relay CXP, back contact 140 of relay CNR, wire 141, front contact 142 of relay CNP, and polar contact 143 of relay CNP in a right hand position, to (-). The picking up of that relay closes a stick circuit at front contact 105 to shunt contacts 140, 142 and 143 out of the circuit just described. It will be noted upon considering the stick circuit for relay CXP that such relay is maintained energized, dependent for deenergization upon the dropping away of the exit relay EXR, as compared to the stick circuit for the relay CXP as shown in Fig. 1B which provides that such relay is dropped away as soon as the through route is established.

When relay CXP is picked up, the relay 2N is picked up, because that relay is selected in preference to relay 2R by the picked up position of the relay 2Y, upon the energization of a circuit closed from (+), including front contact 144 of relay CXP, wire 145, front contact 65 of relay 2Y, upper winding of relay 2N, and back contact 66 of relay 2R, to (-).

After the track switches have properly responded to correspond with the picked up position of the relays 2N and 3N, the relays 2LS and 3LS are dropped away, and a signal control circuit is established to cause the picking up of relay B1G, from (+), including front contact 91 of relay EXR (see Fig. 3B), front contact 92 of relay 3NCR, back contact 83 of relay 3RCR, back contact 84 of relay 3LS, front contact 85 of relay 3TR, back contact 146 of relay CXR¹, front contact 147 of relay CXP, wire 148, back contact 149 of relay CXR, front contact 150 of relay 2TR, back contact 151 of relay 2LS, back contact 152 of relay 2RCR, front contact 153 of relay 2NCR, back contact 154 of relay BXR, front contact 155 of relay B1NR, and winding of relay B1G, to (-).

The picking up of the relay B1G closes contacts 201 and 202 so as to cause the signal mechanism B1 to be energized, and the polarity of such energization is determined in accordance with whether the next running signal in advance, namely, signal G, is at stop or is cleared. If the signal G is at stop, its green-yellow repeating relay GGYP closes back contacts 203 and 204 so as to supply energy to the signal mechanism B1 of such a polarity as to actuate its yellow roundel Y to an active position and cause the signal B1 to give a caution signal aspect, that is, approach the next running signal prepared to stop. On the other hand, if the signal G is clear and the relay GGYP is picked up to close front contacts 203 and 204, then the signal B1 is energized with such polarity as to actuate its green roundel G to an active position causing such signal to display a high speed proceed signal aspect.

As above mentioned, the directional stick relay 3ES of Fig. 2 has substituted therefor the directional stick relay 3ES¹ in this form of the present invention. This relay 3ES¹ is normally energized by a circuit closed from (+), including front contact 162 of relay 2ES, back contact

163 of relay CG, front contact 164 of relay 3TR, winding of relay 3ES¹, to (-). Contact 169 of relay 3ES¹ shunts track contact 164 to provide a stick circuit characteristic of all directional stick relays. Thus, when the relay B1G is picked up, contact 11 is opened and deenergizes relay 2ES which opens its front contact 162 causing the deenergization of relay 3ES¹. This means that the entire route in advance of the signal B1 up to the next running signal is locked.

The relay 3ES¹ is used in place of the relay 3ES of Fig. 2 when the route establishing means of Figs. 3A and 3B is employed in order that the route locking will become effective past the signal C at stop when signal B1 is cleared.

From the above described circuits, it will be obvious that the signal B1 governs the entire route from signal B1 to signal E past the signal C the same as if such signal were not there. That is, the route is completely established between those points, and the signal control circuit for the signal B1 checks that such route is established and that the track sections included in such route are unoccupied by a train.

It is to be understood, that a route established in this manner governed by the signal B1 may be restored to stop in the same way as explained for other signals, namely, merely by the pulling out of the button BNB to deenergize the stick circuit for the relay B1NR. Deenergization of the relay B1NR not only opens the signal control circuit at front contact 155 for relay B1G but also deenergizes the initiating network at open front contact 56.

On the other hand, if the signal B1 is not manually restored, a train may accept the signal and pass onto the track section 2T causing relay 2TR to be deenergized opening front contact 205 to automatically deenergize the relay B1NR. The deenergization of the relay B1NR opens front contact 155 and removes energy from the signal relay B1G returning the signal B1 to stop.

The deenergization of this relay B1NR also opens front contact 56, removing (B+) energy from the initiating network and deenergizing the relays 2Y, CNP and EXR. The opening of front contact 91 of the relay EXR of course opens the energizing circuit for the signal control relay B1G at a second point.

Although the initiating network for this route from B to E is deenergized, the relays 2N and 3N are maintained energized by reason of their stick circuits as typically shown in Fig. 2 for the relay 3N which has a stick circuit closed by back contact 93 of the relay 3L. It is noted in this connection that the entrance of a train onto the track section 2T maintains the directional stick relay 2ES deenergized as well as the directional stick relay 3ES¹ although the relay B1G is dropped away. As the train passes onto the track section 3T, the relay 2ES is allowed to pick up releasing the track switch 2 but the relay 3ES¹ is maintained deenergized by reason of open front contact 164 of the relay 3TR. When the train passes beyond the signal G, which may be an automatic signal, or may be a manually controlled signal such as B1, for example, the track switch 3 is also released.

Thus, it is seen that a train in passing over a route which has been established by through route control and governed by running signals, is released section by section as the train goes over such route.

If in designation of an entrance point by the actuation of button BNB, an operator rotates 75

that button counterclockwise to an operating position, the relay B2NR responds to such designation and applies a polarity to the initiating circuit network opposite to the polarity applied upon 5 the picking up of relay B1NR. Upon the application of such energy to the initiating circuit network the relay 2Y is picked up by the energization of a circuit closed from (B-), including front contact 156 of relay 2TR (see Fig. 3A), 10 front contact 55 of relay B2NR, back contact 56 of relay B1NR, back contact 57 of relay BXR, back contact 58 of relay 2R, and winding of relay 2Y, to (CN). Upon the picking up of relay 2Y relay CNP is picked up by the energization of a 15 circuit closed from (B-), including front contact 156 of relay 2TR, front contact 55 of relay B2NR, back contact 56 of relay B1NR, back contact 57 of relay BXR, back contact 58 of relay 2R, front contact 59 of relay 2Y, and winding of 20 relay CNP, to (-). When relay CNP is picked up, the through route connection extending through to the initiating network illustrated in Fig. 3B is opened by the polar contact 99 (see Fig. 3A) which is operated to a left hand position, thus rendering the designation of an exit point by the depression of button EXB ineffective for causing the establishment of a route.

It is therefore required, because an operator has designated the shunt signal B2 as an entrance point, that the establishment of a route extending from such entrance point can be effected only upon the depression of button CXB for an exit point. Upon the depression of that button, under such conditions, the exit relay CXR is picked up by the energization of a circuit closed from (B-), including front contact 156 of relay 2TR, front contact 55 of relay B2NR, back contact 56 of relay B1NR, back contact 57 of relay BXR, back contact 58 of relay 2TR, front contact 59 of relay 2Y, front contact 99 of relay CNP, polar contact 99 of relay CNP in a left hand position, winding of relay CXR, wire 69, back contact 61 of relay CXR, and contact 62 of button CXB closed in a depressed position, to (CN). The picking up of relay CXR closes a stick circuit at front contact 63 to shunt contacts 61 and 62 out of the circuit just described.

Responsive to the picking up of relay CXR, the relay 2N is picked up as selected by the picked up position of relay 2Y, and the track switch 2 is operated to a normal position in a manner which has been described. The dropping away of the relay 2LS after the track switch has been properly positioned closes a branch of the signal control circuit for the signal control relay B2G, but the picking up of that relay is delayed until the route for the next track portion in advance is established and the signal C is cleared, all of which general mode of operation is provided in accordance with the railway operating requirements of foreign practice.

Although the signal B2 can be cleared only by the designation of the signal location B as an entrance point and the signal location C as an exit point, it is required that such a shunt signal cannot be cleared unless the next shunt signal in advance is also cleared. Inasmuch as the intermediate shunt signal C cannot be cleared by through route control, then it must be cleared by designating the signal location C as an entrance point and the signal location E, for example, as an exit point.

In other words, it would appear that the clearing of a shunt signal is made dependent upon the clear condition of all intermediate shunt sig-

nals between it and the next running signal location or some arbitrarily chosen point such as a station platform. For the purposes of the present embodiment of the invention, it has been assumed that the signal G is a running signal of the automatic type so that the shunt signal C may be cleared independently of whether the signal G is the clear or stop. However, it might be desirable under certain circumstances that the shunt signal C be dependent upon some shunt signal at the signal location G or at some successive point, and this is to be considered within the scope of the invention. Also, for convenience in the disclosure, the signal location D has been shown as having a shunt signal F but it is assumed that it is the entrance to a station platform or the like and the shunt signal C may be cleared independently of the clear or stop indications of such signal F. However, if desired, the shunt signal C may be prevented from clearing until the shunt signal F has been cleared in a similar manner as provided for the shunt signals A and B2. More specifically, the shunt signal B1 cannot receive energy for clearing such signal unless front contact 165 of the signal control relay CG is closed (see Fig. 3B). This energizing circuit for the signal control relay B2G will be pointed out more in detail hereinafter.

In view of the fact that the shunt signal B2 cannot clear until the shunt signal C has been cleared, it would seem logical that the manipulations should be made for the route over which the shunt signal is to govern prior to the making of the manipulations for the route from B to C, although such order of manipulation for these signals is not required.

Having pointed out how the route between the signal location B and the signal location E is established, although the signal B2 has not cleared, it will now be pointed out how the route from the signal location C to the signal location D is established and the shunt signal C cleared after which the signal B2 immediately clears.

Having considered the establishment of the route from signal B2 to signal C, assume that an operator then proceeds to designate an entrance point at signal C by the rotation of the button CNE, which causes the picking up of relay CNR by the energization of an obvious circuit (see Fig. 3B). The picking up of relay CNR conditions each of the relays DXR and EXR for energization when its respective exit button XB is actuated. It will be assumed, for the purpose of illustration, that an operator designates an exit point at signal D by the depression of button DXB. The depression of such button causes the picking up of relay DXR by the energization of a circuit closed from (B-), including front contact 157 of relay 3TR, back contact 158 of relay CXP, front contact 36 of relay CNR, back contact 38 of relay CXR¹, back contact 39 of relay 3N, winding of relay DXR, back contact 40 of relay DNR, and contact 41 of button DXB closed in a depressed position, to (CN). The picking up of that relay closes a stick circuit at front contact 42 and polar contact 170 to shunt contacts 40 and 41 out of the circuit just described.

Responsive to the picking up of relay DXR, the relay 3R is picked up to cause the track switch 3 to be operated to a reverse position in a manner which has been described, and the dropping away of relay 3LS after such track switch has been properly positioned causes the picking up of the

signal control relay CG for the clearing of signal C by the energization of a circuit closed from (+), including polar contact 172 of relay DXR in a left hand position, front contact 81 of relay DXR, back contact 82 of relay 3NCR, front contact 83 of relay 3RCR, back contact 84 of relay 3LS, front contact 85 of relay 3TR, back contact 46 of relay CXR¹, back contact 159 of relay CXP, front contact 160 of relay CNR, and winding of relay CG, to (-). The picking up of relay CG causes the clearing of signal C in accordance with the closing of front contacts 210 and 211 for application of energy to the mechanism search light signal C of the proper polarity to cause it to give a yellow proceed indication.

Upon the clearing of signal C, the route locking relay 3ES¹ (see Fig. 4) is dropped away by the opening of back contact 163. When relay 3ES¹ is dropped away, a circuit is closed to cause the picking up of the relay B2G (see Fig. 3A) for the clearing of signal B2 from (+), including front contact 165 of relay CG (see Fig. 3B), back contact 166 of relay 3ES¹, wire 167, front contact 149 of relay CXR, front contact 150 of relay 2TR, back contact 151 of relay 2LS, back contact 152 of relay 2RCR, front contact 153 of relay 2NCR, back contact 154 of relay EXR, back contact 155 of relay B1NR, front contact 168 of relay B2NR, and winding of relay B2G, to (-). The picking up of relay B2G applies energy of the proper polarity at front contacts 212 and 213 to cause the signal B2 to display a yellow proceed indication.

From the circuits just described it is therefore believed to be obvious that the clearing of the shunt signal B2 depends upon the clearing of a shunt signal C, but it is not necessarily required that the operator designate the route governed by signal C prior to the designation of the route governed by signal B2. That is, the route governed by signal B2 can be designated first, and the route governed by signal C afterward as has been described, or such routes can be designated in the inverse order as desired by the operator.

It should also be noted from the circuits just described, that the signal C can be cleared independent of signal B2, as would be desirable in switching over track switch 3.

The restoration to normal of the parts of the system when the circuits are provided in accordance with Figs. 3A and 3B, is effective in a manner very similar to that which has been described, except that automatic restoration is effective for the shunt signals as well as the running signals. That is, for example, when a route is established from signal B2 to signal C, the entrance of a train in the track section 2T causes the dropping away of 2TR, and the opening of the stick circuit for relay CXR at front contact 156. The dropping away of that relay opens the signal control circuit for relay B2G at front contact 149. The dropping away of relay B2G causes the signal B2 to be restored to stop and the dropping away of relay CXR causes the restoration of the route establishing means in a manner similar to that which has been described. The relay B2NR is not restored under such conditions, however, until an operator restores the button BNB to its normal position. Such circuit organization provides that automatic restoration is effective upon passage of a train, but the setting up of a route for the next train approaching that signal can be effected when there is a route available by actuation of the exit button only for such route, providing of course, that the exit point can

be designated within the same interlocked group in which the entrance point involved, such, for example, as an exit point at signal C when relay B2NR is maintained energized for an entrance point.

The means employed for the embodiment of the present invention thus appears to be readily adaptable to certain practices of foreign railroads in the control of so-called shunt signals and their relationship to associated running signals. The ordinary train movements through the interlocking plant of such a railroad apparently are made on running signals, while the shunt signals are employed to make switching moves of shorter length than would be required if the running signals were employed to make such train movements. For example, a train could move from D past the signal location C with the track switch 3 reversed and then receive a clear shunt signal at C to go over the track switch 3 normal past the signal location G. If it were not for the shunt signal C such a train would of necessity have to go beyond the signal location B before receiving a back-up signal.

Summary

After considering both the detail and the general aspects of the embodiments of the present invention, it is seen that there are certain principles involved which may not only have use in the connection shown but in various other connections in entrance-exit type interlocking systems. One of these main principles is that initiating circuits may be characteristically energized in a manner to limit or allow energy flow past intermediate signal locations. This may be for the purpose of determining the class of signal to be cleared or for various other purposes in the adaptation of an entrance-exit interlocking system employing the principle of preselection of routes. It is of course to be understood that this broad principle may be embodied in various forms and utilized in various ways to accomplish the purposes intended, which are intended to be within the scope of the present invention. It will, of course, be realized that through-route control has been previously disclosed, such as in the prior application of S. N. Wight et al., Ser. No. 245,384, filed December 13, 1938, now U. S. Patent 2,219,502 granted October 29, 1940, but the present invention is more particularly directed to the manner in which such through-route control is limited to manipulations of the control buttons characteristic of the signals which are employed for governing trains over the through routes thus established. It is also to be understood that such features may also be accomplished by other means than by polarizing the initiating circuits of a system employing preselection, but the present invention is to be considered of such a scope as to cover all such means which may be considered equivalents of the means disclosed herein for accomplishing this type of through-route control.

Having described an entrance-exit system as provided for a specific type of a track layout as one specific embodiment of the present invention, it is desired that this form is selected primarily to facilitate in the disclosure of the present invention as to the principles involved and mode of operation, rather than to limit the number of forms which the invention may assume; and it is to be further understood that various modifications, adaptations and alterations may be applied to the specific form shown to meet the re-

quirements of practice, without in any manner departing from the spirit or scope of the present invention except as limited by the appending claims.

5. What I claim is:

1. In a switch and signal control system of the entrance-exit type for governing traffic in a track layout having a plurality of interlocked groups located end-to-end and having power operated track switches to set up different routes between the signal locations of the different groups and including at least one through route past an intermediate signal location, high speed and low speed signals for the signal location governing the entrance to said through route and also for said intermediate signal location, manually operable control buttons for designating the entrance and exit points of routes in each interlocked group and for said through route, said buttons for designating entrance points having distinctive positions for selecting a high speed signal or a low speed signal for such points, route establishing means for each interlocked group responsive to the designation of the entrance and exit points of that group for establishing routes connecting such points and clearing a low speed or high speed signal for the entrance signal location in accordance with the distinctive operated position of the control button designating the entrance point, and through route means for interconnecting the route establishing means of the adjacent interlocked groups at such intermediate signal location for establishing routes in such adjacent interlocked groups and clearing the high speed signals for the respective entrance points, said through route means effectively providing such interconnection only if the entrance point to such through route has been designated by operating its control button to select a high speed signal, whereby the designation of the entrance and exit points of said through route can be effective only providing said manually operable control button is operated to a position for selecting a high speed signal.
2. In a switch and signal control system of the entrance-exit type for a track layout having power operated track switches to provide a plurality of conflicting routes extending between entrance and exit points, such track layout being divided into a plurality of interlocked groups located end-to-end to provide at least one through route past an intermediate signal location, a high and a low speed signal for governing traffic at the entrance to each of said interlocked groups for one direction of traffic, manually operable contact means for designating the entrance and exit ends of routes and having distinctive operated positions for selecting a high or a low speed signal for governing the entrance to an established route, an exit relay for the exit end of each of the routes in an interlocked group, initiating circuit means responsive to the designation of any given entrance point for conditioning for energization the exit relay for each available route originating at that given entrance point, whereby the designation of the exit end of any one of such available routes effects the energization of the corresponding exit relay, route establishing means for each interlocked group controlled by the picking up of the exit relay at the end of an available route having its entrance and exit ends designated for causing that route to be established and the high or low speed signal cleared at the entrance thereto depending upon the distinctive operated position of said entrance

contact means, and through route circuit means controlled over said initiating circuit means in response to the designation of the entrance signal location to clear said high speed signal for interconnecting said initiating circuit means for the adjoining interlocked groups so as to condition for energization said exit relay for the exit end of said through route, said through route circuit means being ineffective if the designation of said entrance point for said through route was to select a low speed signal, and signal clearing circuits effective after a route is established for clearing a high speed signal or a low speed signal for governing the entrance to such route in accordance with the distinctive operated position of the manually operable contact means for the corresponding entrance point, such means also being effective upon the establishment of a through route to clear each intermediate high speed signal included in such through route.

3. In a switch and signal control system of the character described for governing traffic through a track layout comprising at least one power operated track switch and its governing signals capable of providing a plurality of routes extending from a given entrance point to a plurality of exit points, at least one of such routes permitting high speed traffic and at least one other of such routes permitting low speed traffic; a high and a low speed signal for governing traffic at said entrance point; manually operable contact means for said entrance and exit points, said contact means for said entrance point having different operated positions to select whether said entrance point is to be governed by said high speed signal or by said low speed signal; and route establishing means responsive to the operation of said manually operable contact means for the exit point of any given one of said routes following the operation of the manually operable contact means for said entrance point to establish the corresponding route, said means being responsive to establish said high speed route irrespective of the operated position of the contact means for said entrance point, but being effective to establish said low speed route only providing said contact means for said entrance point is in a position to select said low speed signal.

4. In a switch and signal control system of the character described for governing traffic through a track layout having at least one power operated track switch and a plurality of routes extending from a given entrance point to a plurality of exit points; a high and a low speed signal for governing traffic at said entrance point; manually operable contact means for said entrance and exit points, said contact means for said entrance point having different operated positions to select whether said entrance point is to be governed by said high speed signal or by said low speed signal; an exit relay for each of the exit points, said exit relay for a particular one of such exit points being distinctively responsive to different conditions of energization; circuit means responsive to the actuation of said contact means for said entrance point and the subsequent actuation of said contact means for any one of said exit points for distinctively energizing said exit relay for that exit point in accordance with whether said contact means has been operated to a position to select said high or said low speed signal; and route establishing means responsive to the energization of said exit relay

for any given one of said routes for causing the power operation of said track switch as required to set up that route, said route establishing means being responsive to the energization of said exit relay for said particular exit point only if that relay is distinctively energized in accordance with the operation of said contact means for said entrance point to a position for selecting said low speed signal.

5. In a switch and signal control system of the character described for controlling power operated track switches to establish different routes between an entrance point and a plurality of exit points, a high speed and a low speed signal for governing traffic into said routes at said entrance point, manually operable contact means for said entrance and exit points, said contact means for said entrance point having distinctive operated positions by which an operator can pre-select for clearing either said high speed signal or said low speed signal; an exit relay for each of said exit points, circuit means conditioned in response to the actuation of said contact means for said entrance point for energizing the exit relay for any given available route originating at said entrance point having the contact means for such exit point operated, route establishing means responsive to the energization of an exit relay for the exit end of a particular one of said routes following the actuation of said contact means for the entrance and exit ends of such route for causing the power operation of the track switch or switches required to establish that route only if said entrance point has been designated by the operation of its contact means to a position to preselect said low speed signal, said route establishing means being responsive to the energization of the exit relay for the exit end of another of such routes following the actuation of the contact means for the entrance and exit ends of such route irrespective of the operated position of the contact means for the entrance point for causing the power operation of the track switch or switches required to establish such another route, and signal control circuits rendered effective in response to the complete establishment of any given route for clearing said high speed or said low speed signal in accordance with the operated position of said contact means for said entrance point and in accordance with the response of said route establishing means to such operated position of said contact means.

6. In a switch and signal control system of the character described for controlling power operated track switches and signals to establish any one of a plurality of conflicting routes between an entrance point and a plurality of exit points, at least one of such routes permitting high speed traffic and at least one other of such routes permitting low speed traffic, a high and a low speed signal for governing traffic at said entrance point, manually operable contact means for said entrance point having a plurality of operated positions by which an operator can select a high speed signal or a low speed signal, manually operable contact means for each of said exit points, circuit means responsive to the operation of said contact means for said entrance point for conditioning each of said exit relays for distinctive energization upon the actuation of the manually operable contact means for the corresponding exit point in accordance with whether said contact means for said entrance point has been operated to select a high speed

signal or a low speed signal, said circuit means being effective only if there is an available route extending between said entrance point and that exit point, route establishing means effective to establish said high speed route in response to the energization of the exit relay for the exit end of that high speed route irrespective of the character of such energization, and effective to establish said low speed route in response to the energization of the exit relay for the exit end of that low speed route only if the energization of such exit relay by said circuit means has been characterized in accordance with said manually operable contact means for said entrance point being in an operated position to select said low speed signal, and signal clearing circuits for clearing said high and low speed signals, said circuits being effective to clear either signal in accordance with the position of said manually operable contacts for said entrance point when said high speed route is established, but being effective to clear only said low speed signal when said low speed route is established.

7. In a switch and signal control system of the character described for governing traffic through a track layout having at least one power operated track switch to provide routes extending from an entrance point to a plurality of different exit points; a high and a low speed signal at said entrance point for governing the entrance of traffic to said routes; manually operable contact means for said entrance and exit points, said contact means for said entrance point having distinctive operated positions for selecting said high or said low speed signal; electro-responsive means for each of the exit points, said electro-responsive means for a particular one of such exit points having a contact which is closed only when that electro-responsive means is energized with a particular polarity; a circuit network having circuit portions corresponding to the routes extending through said track layout and supplied with energy of one polarity when said contact means for said entrance point is operated to select said high speed signal and supplied with energy of the opposite polarity when said contact means for said entrance point is operated to select said low speed signal, and said circuit means being effective upon the actuation of said contact means for the exit point of any given route following the actuation of said contact means for said entrance point to energize the electro-responsive means for that exit point if such route is then available for use; and route establishing means initiated into operation upon the energization of the electro-responsive means for the exit end of any given route to cause the operation of said track switch to set up that route, said route establishing means being initiated into operation by said electro-responsive means for said particular exit point only if that electro-responsive means is energized with said particular polarity to close its said contact.

8. In a switch and signal control system of the character described for governing traffic through a track layout having at least one power operated track switch to provide routes extending from an entrance point to a plurality of different exit points; a high and a low speed signal at said entrance point for governing the entrance of traffic to said routes; manually operable contact means for said entrance and exit points, said contact means for said entrance point having distinctive operated positions for selecting said high or said low speed signal; an exit relay for each

5 of said exit points, said exit relay for a particular one of such exit points being of the polar-neutral type; a circuit network having circuit portions corresponding to the routes extending 10 through said track layout and supplied with energy of one polarity when said contact means for said entrance point is operated to select said high speed signal and supplied with energy of the opposite polarity when said contact means for said entrance point is operated to select said low speed signal, and said circuit means being effective upon the actuation of said contact means for the exit point of any given route following the actuation of said contact means for said entrance point to energize the corresponding exit 15 relay of that route if it is then available for use; and route establishing means rendered active upon the energization of the exit relay for any given route to cause the power operation 20 of said track switch as required to set up that route, said route establishing means being responsive to the energization of said polar-neutral exit relay for said particular exit point only if that relay is energized with a polarity determined in accordance with the operation of said contact means for said entrance point to a position for selecting said low speed signal.

9. In a switch and signal control system of the character described for governing traffic 30 through a track layout having power operated track switches to provide routes between signal locations constituting entrance and/or exit points for such routes; manually operable contact means for said signal locations for designating the corresponding locations as entrance or exit points, said contact means for at least one of said entrance points having two different operated positions; electro-responsive means for each of the exit points, said electro-responsive means for a 35 particular one of such points being distinctively actuated when that electro-responsive means is energized with a particular polarity; initiating circuit means energized upon the actuation of any given manually operable contact means to 40 designate an entrance point acting to preselect the positions of the trailed switches in all routes originating at the corresponding signal location, said circuit means being supplied with energy of one polarity when said contact means for said one entrance point is operated to one of its two different operated positions and supplied with energy of the opposite polarity when said contact means for said one entrance point is operated to the other of its two different operated positions, and said initiating circuit means being 45 effective upon the actuation of the contact means for the exit point of any given route following the actuation of the contact means for the entrance end of that route to energize the electro-responsive means for that exit point in accordance with the polarity supplied to said initiating circuit means if such route is then available for use; and completion circuit means initiated into 50 operation upon the energization of the electro-responsive means for the exit end of any given route to cause the power operation of the track switches in accordance with said preselection by said initiating circuit means and as required to set up that route, said completion circuit means being initiated into operation following the operation of said contact means for said particular exit point only if the electro-responsive means for that point is distinctively actuated.

10. In a switch and signal control system of the entrance-exit type for governing traffic in a track

layout having power operated track switches for setting up different routes between a first and second signal location and also between said second signal location and a third signal location, manually operable control buttons for said signal locations for designating the corresponding locations as entrance or exit points, route establishing means responsive to the designation of said first signal location as an entrance point followed by the designation of said second signal location as an exit point for establishing a route between such locations, another route establishing means responsive to the designation of said second signal location as an entrance point followed by the designation of said third signal location as an exit point for establishing a route between such signal locations, and signal control circuits for clearing the signals at said first and second signal locations when said route establishing means has been effective to establish said routes, said signal control circuits being so organized as to require said signal at said second signal location to be cleared prior to the clearing of the signal at said first signal location, whereby said signals at said first signal location can be cleared only if said signal at said second signal location has been cleared in response to manipulations designating the second signal location as an entrance point followed by the designation of said third signal location as an exit point.

11. In a switch and signal control system of the entrance-exit type for governing traffic in a track layout having two spaced running signals governing traffic in the same direction with a shunt signal at said first running signal location and an intermediate shunt signal also governing traffic in that direction, said track layout including power operated track switches to set up different routes between the signal locations, manually operable control buttons for said signal locations for designating the corresponding signal location as an entrance or exit point of a route, said button for designating the first running signal as an entrance point having distinctive positions for selecting said running signal or said shunt signal for such location, route establishing means associated with that portion of track between said first running signal and said intermediate shunt signal responsive to the operation of the control button associated with that signal to a position to select said shunt signal followed by the operation of said control button to designate said intermediate shunt signal as an exit point for establishing a route between such points, route establishing means for that portion of track between said intermediate shunt signal and said second running signal responsive to the designation of said intermediate shunt signal as an entrance point and the designation of said second running signal as an exit point for establishing a route between such points, means interconnecting said route establishing means for the two adjoining portions of track to render said route establishing means responsive to the operation of said control button associated with said first running signal to a position to select said running signal followed by the operation of the control button associated with said second running signal to cause the response of both route establishing means to establish a route connecting said two running signals, and signal control circuits for clearing said first running signal independently of said shunt signal remaining at stop.

12. In a switch and signal control system of the entrance-exit type for governing traffic through

5 a track layout including a plurality of power operated track switches between first and second signal locations, said first signal location having a running signal and a shunt signal and there being a shunt signal intermediate to said running signals, manually operable control buttons associated with said signal locations for designating the corresponding location as an entrance or exit point of routes, said button for said first signal location being operable to either of two operated positions for selecting said running signal or said shunt signal, route establishing means associated with said track layout and responsive to the actuation of the control buttons for said intermediate signal and said second signal location to designate such location as entrance and exit points respectively and also the actuation of the control buttons for said first signal location and said intermediate signal location to designate such location as entrance and exit points respectively for causing a route to be established between said signal locations and the clearing of said shunt signals at said first signal location and the said intermediate signal location, and means acting on said route establishing means in response to the operation of said control button for said first signal location to a position to select said running signal followed by the actuation of the control button for said second location designating it as an exit end of a route to cause a route to be established between such signal locations and to cause the clearing of said running signal at said first signal location without the clearing of said intermediate shunt signal.

35 13. In a switch and signal control system of the entrance-exit type for governing the power operation of switches to establish routes between signal locations at the ends of such routes and through routes past at least one intermediate signal location comprising, a control panel having thereon a miniature track diagram of the track layout, freely movable manual control devices associated with points on said track diagram corresponding to the signal locations at the entrance and exit ends of said routes, certain of said control devices having different distinctive positions, initiating circuit means energized by the operation of a manual control device to a particular distinctive position to designate a given point as the entrance end of a through route for pre-selecting the position of the trailed switches included in all of the establishable through routes originating at that point and passing said intermediate signal, and means controlled by said initiating circuit means when the manual control device is operated to a different distinctive position to designate said given point as an entrance end of a route for limiting the preselection operation of said initiating circuits to only the various establishable routes originating at that point without passing said intermediate signal.

65 14. In a switch and signal control system of the entrance-exit type for track layouts affording one or more through routes over two adjoining interlocked groups past an intermediate signal location, manual control devices for designating the signal locations of said track layout to constitute the entrance or exit ends of the desired routes or through routes, a route establishing means for each of said interlocked groups for operating the track switches in its group to positions to establish any given route in that group, and circuit means responsive to the actuation of a manual control device to designate any given entrance signal location to prepare for operation said route

establishing means for each of those said interlocked groups involved in any through route originating at said entrance signal location, and means for at times preventing said circuit means to condition said route establishing means for through route operation past said intermediate signal location responsive to the distinctive operation of a manual control device to designate the entrance end of that particular through route.

15. In a switch and signal control system of the entrance-exit type for track layouts affording one or more through routes over two adjoining interlocked groups, said system comprising manual control devices for designating the signal locations of said track layout to constitute the entrance or exit ends of desired routes or through routes, route establishing means for each of said interlocked groups to set up the different routes between the signal locations of that group, circuit means responsive to the actuation of a manual control device to designate a given entrance signal location to prepare for operation of said route establishing means for those of said interlocked groups involved in any through route originating at said entrance signal location providing said manual control device has been actuated to a particular distinctive position, said circuit means preparing for operation the route establishing means of only its own interlocked group if such device has been operated to a different distinctive condition, the actuation of a manual control device to designate the exit signal location of a particular one of said through routes rendering the route establishing means of the remote group effective to establish a route through that group to the entrance signal there-of constituting an intermediate signal in that particular through route, electro-responsive means associated with each intermediate signal location and responding to the establishment of a route from that signal location through the remote interlocked group to control the clearing of that signal and to exercise a control on the route establishing means of the adjoining interlocked group the same as if the manual control device for such intermediate signal location had been operated.

16. In a switch and signal control system of the entrance-exit type for governing traffic in a track layout having a plurality of interlocked groups located end-to-end and having power operated track switches to set up different routes between the signal locations of the different groups and including through routes, a control panel having thereon a miniature track diagram of the track layout, freely movable manual control devices associated with points on said track diagram corresponding to said signal locations and operable to designate such signal locations as the entrance or exit ends of routes, said control devices for certain of said signal locations being operable to either of two distinctive positions, initiating circuit means energized by the operation of any manual control device to designate the corresponding entrance signal location for preselecting the position of the trailed switches included in all of the establishable routes or through routes originating at that entrance signal location, said initiating circuit means in the case of the designation of an entrance signal location by the operation of its manual control device to one of its distinctive operated positions for preselecting the position of the trailed switches for the routes originating at that location and included in only the associ-

ated interlocked group, but acting in response to the operation of such device to the other of its distinctive operated positions to preselect the position of the trailed switches included in all of the routes originating at that signal location including said through routes, and completion circuit means responsive to the subsequent actuation of a manual control device to designate an exit signal location for a particular one of said route or through routes for controlling the operation of switches dependent upon the initiating circuits energized and thereby establishing said route, said means responding to the operation of a manual control device to designate an exit signal location of a through route only providing that said preselection operation has been effective by said initiating circuits for such through route.

17. In a switch and signal control system of the entrance-exit type for governing the power operation of switches to establish different routes over a track layout between entrance and exit points comprising, a control panel having thereon a miniature track diagram of the track layout, freely movable manual control devices on said track diagram at points corresponding to said entrance and exit points of said track layout, certain of said control devices being operable to at least two different operated positions, initiating circuit means energized by the operation of manual control devices to either operated position to designate an entrance point for preselecting the position of the trailed switches included in all of the available routes originating at that point, said initiating circuit means being distinctively energized with current of one character or another in accordance with the position to which said manual control device is operated to thereby condition the manual control devices for the exit ends for certain of said available routes when said initiating circuit means is energized with current of one character, and to thereby condition the manual control devices for the exit ends of other available routes when said initiating circuit means is energized with a current of a different character, and completion circuit means responsive to the subsequent actuation of a manual control device that has been conditioned at the exit end of a particular available route to cause the power operation of the track switches in accordance with said preselection by said initiating circuit means to thereby establish that particular route.

18. In a switch and signal control system of the entrance-exit type for governing the power operation of switches to establish routes or through routes over a track layout between entrance and exit points comprising, a control panel having thereon a miniature track diagram of the track layout, freely movable manual control devices on said track diagram at points corresponding to said entrance and exit points of said track layout, certain of said control devices being operable to at least two different distinctive positions, initiating circuit means energized with current of one polarity by the operation of the manual control device to one distinctive position but energized with current of the opposite polarity by the operation of a manual control device to the other distinctive position, said initiating circuit means selectively determining in accordance with the polarity of energization which of the available routes or through routes originating at the designated entrance point can be selected for establishment, and completion circuit means

responsive to the subsequent actuation of a manual control device to designate the exit end of one of the available routes selected by said initiating circuit as being establishable to cause the power operation of the track switches as required to establish that particular route.

19. In a switch and signal control system of the entrance-exit type for track layouts including a plurality of interlocked groups and affording one or more through routes past at least one intermediate signal location between extreme entrance and exit signal locations, manual control devices on a control panel manually operable to designate the entrance and exit ends of some desired route or through route, certain of said control devices being operable to at least two different operated positions, initiating circuit means energized with current of one polarity by the operation of a manual control device to one operated position, and energized with current of the opposite polarity by the actuation of said manual

control device to its other operated position, said initiating circuit means acting to preselect the position of the switches included in only its interlocked group when energized with said one polarity but acting to preselect the position of the switches in all of the available routes and through routes originating at the designated entrance point when energized with current of the opposite polarity, and completion circuit means responsive to the subsequent actuation of a manual control device to designate the exit end of a particular one of said routes having its switches preselected for causing the power operation of the track switches to establish that particular route or through route, whereby the distinctive operation of a manual control device at an entrance signal location determines whether a route or a through route may be established by distinctively energizing the initiating circuits with current of one polarity or the other.

NELSON B. COLEY.
